REGULATING SYSTEM

Arnold P. Hayward, Bellevue, and Thomas E. Purcell, Pittsburgh, Pa.

Application April 19, 1932, Serial No. 606,200

47 Claims. (Cl. 290—4)

Our invention relates to regulating systems and has particular relation to systems for automatically transferring, in accordance with a predetermined schedule, the control of a load-adjusting device from one to another of a plurality of parallel-operated machines.

Our invention has particular applicability to electrical power systems, it being capable of adjusting in a maximum-power-system efficiency or other predetermined manner the distribution of load among a plurality of electrical generating units which operate in parallel to supply a variable-demand system load.

Due to the rapid growth in the capacity and extensiveness of electrical power systems, features of operating economy and efficiency are assuming increasingly greater importance, and it is with such features that the system of our invention is primarily concerned.

Present day power systems utilize a relatively large number of separate generating units which operate in parallel to supply a common load. In a large percentage of cases, this load may vary over a considerable range, the power demand on many generating stations normally being of a fluctuating nature.

The past practice of allowing each of the several parallel-operated units to assume a pro rata share of the total load supplied as the magnitude of demand changes, prevents, particularly when the units have different load-efficiency characteristics, the highest operating economy from being realized when the total load is varied throughout a substantial range.

The distribution of load among the several units which is most advantageous, for any given value of total output, must thus take account of the inherent efficiency of each of the generating units, and, in many cases, of certain other factors. It will be evident, therefore, that increased operating economy of an electrical power system can be obtained through a proper control of load distribution among the several generating units in the system.

To be of the greatest utility, it is apparent that a system of load-distribution control should be self-operating or automatic, and susceptible of being pre-set for any loading combination among the generating units which may prove most desirable.

The system of our invention possesses the qualifications above stated and provides means whereby those substantial savings in power-system operating costs which may be effected by predeter-

mined load distribution among the several supply sources are effectively realized.

In U. S. Patent No. 1,920,544, which issued Aug. 1, 1933 to J. H. Ashbaugh and R. A. Geiselman, and which is assigned to the Westinghouse Electric & Manufacturing Company, there is described a system which automatically transfers the control of a load-adjusting device from one to another of a plurality of electrical generating units in accordance with changes in the total load supplied by all of the units. In that system, to which the term "program-load control" may aptly be applied, transfer operations, which are initiated by contact closure of load-responsive means associated with the generator unit under regulator control, are caused to proceed in accordance with a predetermined program or schedule.

When applied to a power system, this program-load-control equipment acts to route the load-adjusting impulses from a regulator selectively among the several generating units in the station in a manner that total load increments are progressively taken on by individual units selected according to the predetermined program. This program may be chosen to effect a predetermined distribution of load among the generating units which so accords with their efficiency characteristics that the operating economy of the system is thereby raised.

Our invention is directed to an improved form of program-load control system which possesses the features and advantages particularized hereinafter.

There have been proposed regulating systems which function to rigidly maintain the load of all generating units, except the one under regulator control, at fixed values, regardless of the suddenness with which the total load demand may change. Such systems are subject to a marked disadvantage in that the governors of all units are not free to respond to sudden demand changes, and hence the major portion of the generating capacity is ineffective for meeting such demands. In an alternating-current power system involving a transmission line, for example, the stability and power limits of the line are, as a result, substantially diminished by the application of such a regulating system to the generating units which supply the line.

It is, accordingly, a general object of our invention to provide regulating means for a plurality of electrical power sources supplying a common load whereby the distribution of load among the several sources may be automatically adjusted in a predetermined manner, and, at the same

time, the governing means of all of the several sources will be unhampered in their normal ability to respond to sudden changes in total power demand.

5 The program-load-control system disclosed in the copending application above mentioned, while adequate for applications in which the parallel-operated generators are driven by prime movers of the single input-control-valve type, does not, 10 for example, make provision for certain operating conditions which are peculiar to multi-input control valve prime movers.

In the case of a multi-valve steam turbine, for example, it is highly undesirable to operate at 15 certain points in the load range of the turbine. Thus, at those load values where an additional control valve just starts to open, the heat rate becomes unduly high and the valve seat wear is excessive. While in practice such ranges may 20 be rather narrow, the desirability of operating outside of them has long been recognized by steam turbine experts, so that provision should be made, in an automatic transfer system of the type under consideration, to ensure that the 25 generating units supervised will not be permitted to continuously carry loads which cause the driving turbines to operate within these undesirable ranges.

Since, in the majority of present-day steam-powered generating stations of large capacity, the generator driving turbines are provided with a plurality of input control valves, it being found that higher efficiency is thereby obtainable, a 30 program-load-control system which is especially suited for use with multi-valve prime movers is 35 of great utility.

Accordingly, a major object of our invention is to provide a program-load-control system which is especially adapted to effect, in the most economical manner, load increment supervision of 40 a plurality of multi-valve steam turbine driven generating units.

More specifically stated, an object of our invention is to provide a program-load-control system for multi-valve prime mover generating units which is capable of preventing normal operation within those undesirable ranges of unit loading where the prime mover heat rate is high and the valve seat wear is excessive.

50 The system disclosed in U. S. Patent No. 1,920,544 above mentioned is capable of assigning the regulator control to only one of the several generating units under supervision so that the maximum rate of total load change available is limited to the speed with which the single unit can change its output. In certain situations, it may be essential that a higher rate of total load change be available. If the regulator is caused to control the units in groups, as, for example, in 55 pairs, instead of singly, such a higher increment can be obtained, the total change obtainable then being fixed by the approximate sum of load change rates of the units simultaneously controlled. By such an expedient, therefore, the former limitation in total-change rate will be 60 considerably broadened.

65 A further object of our invention, therefore, is to provide means whereby a program-load-control system of the individual-unit control type may, at the will of an operator, be adapted for parallel-pair or other unit group regulator control of the several generating units supervised.

In certain instances, when a multi-generating 75 unit power station is supervised by a program-

load-control system, it may be desired that the transfer equipment be caused to stop on position when it reaches a given unit in its program or sequence of control-transfer operations, as for example when certain of the units are not in a proper operating condition or for any reason should not be supervised by the program controller.

An additional object of our invention therefore, 10 is to provide means whereby the transfer equipment may be caused to stop on position when it reaches any one of the several units supervised.

15 In the operation of a power station comprising a plurality of generating units, it frequently happens that one or more of the units must be taken out of service for repair or adjustment. When supervised by program load control, provision whereby the removal from service of one or more units will not interfere with the operation of the 20 system as regards the remaining units is, therefore desirable.

25 In further object of our invention is the provision in a program load control system of a special control or "skip" switch with each generating unit, which, when closed, will cause the transfer equipment to pass by that particular unit in its sequence of transfer operations, and thus permit functioning of the control system to be unimpaired by the taking out of service of one or 30 more of the generating units.

35 In an automatic system of the type under consideration, it is likewise desirable that some arrangement be employed for minimizing the initiation of transfer operations which are unnecessary or which are subject to immediate reversal. Increased security against the effecting of such 40 operations may be attained by requiring that in addition to contact closure of the transfer initiating means associated with the machine under control the regulator must simultaneously produce a load-changing impulse in the proper direction before a transfer operation can be effected.

45 A still further object of our invention, therefore, is to provide means whereby a transfer operation can be effected only when contact closure of the transfer initiating means is supplemented by a suitable load-changing impulse from the regulator.

50 In a program-load-control system, it is desirable to interrupt the regulator control when a transfer operation, in which the control of the regulator is shifted from the governor of one generating unit to that of another, is being effected in order to prevent arcing at the contact points 55 of the selector device and also to prevent the improper transmission of impulses.

An additional object of our invention, therefore, is to provide means for interrupting the regulator control while a transfer operation is in 60 progress.

65 In controlling the loading of a power station the generating units of which are supervised by program-load-control, it is sometimes desirable to supply the load-adjusting impulses manually instead of from an automatic regulator. For such an arrangement there is a possibility that impulses in both the load-raising and load-lowering directions may simultaneously be set up, which if 70 allowed to reach the load-adjusting devices of the generating units, would cause damage thereto.

75 Accordingly, a further object of our invention is to provide means for preventing load-adjusting impulses in both directions from simultaneously

being sent through the selector equipment to the generating units supervised.

In a control transfer system of the type under consideration, it is customary to segregate certain portions of the equipment in a control room which is remotely situated with respect to the generating units supervised. In order that an operator in this control room may be informed as to the valve positions of each of the turbines, a signal system involving-valve-position indicating lights is, therefore, of utility.

A further object of our invention, therefore, is to provide in a program load control system, a system of indicating lights by means of which the valve positions of each of the generating units supervised may be communicated to an operator at a remote point.

In the operation of a program-load-control system applied to a steam-turbine generating unit power plant, when all of the units under supervision have been fully loaded and the regulator-control transfer equipment has reached its limit of travel in the load-demand increasing or forward direction, further load-raising impulses from the regulator may, if allowed to reach the generating unit to which the regulator is assigned, cause the governor-calibrating motor to continue to increase the tension of the calibration-changing spring even though the completely opened position of all of the turbine valves has been reached. In practice, it is found that when this happens a time delay to responsiveness of the governor to subsequent load-lowering impulses is introduced because the excess tension in the adjusting spring must first be relieved by a reversing action of the motor.

A still further object of our invention, therefore, is to provide means for disconnecting the regulator from the generating units when the full capacity of all of the several units supervised by a program-load-control system has been brought into action.

In practicing our invention, the complete program-load-control system involves, in combination with a regulator or equivalent load-adjusting means for controlling the governor settings of the several turbine generating units supervised, a motor-operated selector switch for transferring regulator control among the generating units and for routing transfer-control circuits, a set of machine and sequence receptacles for changing the transfer operation sequence or program, auxiliary control relays, and turbine-valve-operated switches associated with each generating unit for actuating the selector switch when a control transfer operation is to be effected. In addition, switching devices for permitting the regulator to control the generating units in pairs instead of singly, skip switches for taking one or more of the units out of the program, valve-position-indicating lamps and other auxiliary equipment are also included in the system.

The program-selecting machine and sequence receptacles above mentioned, which are shown in the system of our invention about to be described, are disclosed and claimed in a second U. S. Patent No. 1,907,517, which issued May 9, 1933, to R. De Camp, and which is also assigned to Westinghouse Electric & Manufacturing Company. As is pointed out in that patent, when combined with a program-load-control system, such switching means permit the sequence of transfer operations to be changed at the will of an operator, so that an adjustable or selective program of control transfer is thereby obtainable.

Our invention itself will best be understood through the following description of specific embodiments thereof when taken in conjunction with the accompanying drawings, in which:

Figures 1 and 2, when considered together, are a diagrammatic view of apparatus and circuits arranged in accordance with one preferred form of our invention, which is disposed to automatically effect the transfer of control of a load-adjusting device from one to another of four parallel-operated generating units, each of which is driven by a steam turbine having a plurality of input control valves;

Fig. 3 is a diagram of curves illustrating the heat consumption and heat rate characteristics of a three-valve turbine of the type illustrated in Fig. 1;

Fig. 4 is a diagram showing four sets of heat-consumption curves assumed to respectively apply to the four turbine generating units shown in Fig. 1;

Fig. 5 is a diagram showing the comparative slopes of the several individual sections of the heat consumption curves of Fig. 4 for the purpose of determining the most economical program of transfer operations.

Fig. 6 is a table showing several of the different transfer-operation-sequence schedules which the program-load-control system of Figs. 1 and 2 is capable of effecting;

Fig. 7 is a representation of a typical governing system for a three-valve steam turbine utilizing oil-operated relays intermediate the flyball governor and the turbine valves and illustrating a preferred manner in which valve-position-actuated contacts for all of the valves may be combined into a single-transfer-initiating switch mechanism for operation by the governing system.

Fig. 8 is a section of one of the oil-relay control valves taken on line VIII—VIII of Fig. 7;

Fig. 9 is a plan view of the transfer-initiating switch shown in Fig. 7, with cover cut away, showing the construction and arrangement of the contact members and operating cams of the switch;

Figs. 10 and 11 are sectional views of the transfer-initiating switch shown in Fig. 9 taken on lines X—X and XI—XI, respectively, of that figure.

Fig. 12 is a diagrammatic view of the eight sets of contact members of the switch of Fig. 9 connected in the circuits shown as being associated with generating unit A in the system of Figs. 1 and 2;

Figs. 13 and 14, when considered together, comprise a diagrammatic view of apparatus and circuits combined with the fundamental program-load-control system of Figs. 1 and 2 in such manner that either individual or parallel-pair control operation of the generating units supervised may be effected;

Fig. 15 is a plan view showing the mechanical construction of the motor-operated selector switch which is diagrammatically represented in Figs. 2 and 14;

Fig. 16 is a side elevation view of the switch of Fig. 15;

Fig. 17 is a side elevation view, partially in section, showing the construction of a pair of receptacles and cooperating plug members of a type suitable for use by the program-selecting switching arrangement utilized in the control transfer system shown in Figs. 13 and 14, as well as in the system of Figs. 1 and 2;

Fig. 18 is a simplified schematic representation

of a load-balancing scheme utilized by the parallel-pair control equipment of the automatic transfer system of Figs. 13 and 14;

Fig. 19 is an operation-explanation table showing the several steps or positions assumed by the transfer equipment in the program-load control systems of Figs. 1 and 2 and Figs. 13 and 14; and

Fig. 20 is a diagrammatic view of one of the generating units adapted for parallel-pair operation as shown in Fig. 12 with which the skip switch and valve position indicating lamps depicted in Fig. 1 are combined.

Referring to the drawings, and particularly to Figs. 1 and 2 thereof, it will be observed that the circuit conductors terminating at the right-hand side of Fig. 1 are continued at the left-hand side of Fig. 2 in a manner that the apparatus illustrated in the two figures is interconnected. In the explanation and description which is to follow, like reference characters in the two separate figures will designate conductors which are common to both and which continue from one to the other.

In Fig. 1, the four separate generating units which the program-load-control system of our invention is to supervise are designated generally by units A, B, C and D, respectively. Generating unit A comprises an alternating-current generator 20 disposed to be driven by a prime mover 21, illustrated in the form of a steam turbine. The generator is illustrated as being of the three-phase type comprising armature windings 23 and an exciting field winding 24.

Similarly, generating unit B comprises a generator 25 and a prime mover 26; unit C a generator 28 and a prime mover 29; and unit D a generator 30 and a prime mover 31.

The armature windings of the several generators named are connected in the manner shown to a three-phase power circuit designated by conductors 34, 35 and 36 at the middle of the figures. The generator field windings are illustrated as being energized by direct-current derived from conductors 38 and 40 of positive and negative polarities respectively. These conductors may be supplied from any suitable direct-current energy source (not shown).

Prime movers 21, 26, 29 and 31 are each illustrated in the form of a steam turbine of a well known multi-valve type which is now generally applied in large capacity installations. The turbines may be supplied with driving steam through conduits 42, 43, 44 and 45, respectively, from steam boilers or other suitable source (not shown).

To control the flow of this steam in the most economical manner, a plurality of control valves are inserted in each of the conduits named.

Prime mover 21, for example, utilizes a primary valve 48 which supplies one set of steam jets in the turbine, a secondary valve 49 which supplies a second set of jets, and a tertiary valve 50 which supplies a third set of steam jets. In operation, both the secondary and tertiary valves remain closed until the primary valve has been completely opened, at which time the secondary valve also opens and causes the second set of steam jets to aid the first in driving the turbine. When the secondary valve has been completely opened, the tertiary valve also opens and brings into action the third set of steam jets.

In a similar manner, prime movers 26, 29 and 31 are each provided with primary, secondary, and tertiary input control valves represented in the same relative positions as are the valves of prime mover 21 already described.

The position of the movable members of the control valves is determined by a speed-responsive governor mechanism in a well known manner. As illustrated, prime mover 21, for example, drives through a suitable mechanical connection a flyball mechanism 55 which transmits governing movements to an arm 57 which is shown as being pivoted at its right end and connected at the other end to the control valves by means of members 59, 60 and 61, respectively. An increase in the speed of prime mover 21 acts to move lever 57 downwardly to close the valves, while a decrease in speed similarly acts to move the lever upwardly to open the valves and thus admit more steam.

In a similar manner, the prime movers 26, 29 and 31 are each provided with flyball governing mechanisms which act to control the positions of the input control valves in accordance with the speed of the prime movers. Since the showing of the valve and governing mechanisms for all of the units of Fig. 1 is a duplicate, no further detailed description for units B, C and D is deemed necessary.

The showing of the governing mechanisms in Fig. 1 is greatly simplified as compared with the equivalent actual arrangement utilized by large capacity turbines, one well known form of which is illustrated in Fig. 7 and which will later be described.

Inasmuch as a direct relation exists between the input to the driving prime mover and the output of the driven generator in a generating unit of the type under consideration, changing the input of the steam turbine will cause the generator to correspondingly change its output. It will be observed that, in the case of the particular type of governing mechanism shown, for loadings within the range of the primary valve the secondary valve is closed while for loadings above the primary range the secondary valve is also opened, and for loadings above the combined primary and secondary range, the tertiary valve opens. This particular relation is graphically represented by the curves of Fig. 3 which will be more completely explained hereinafter.

The governing mechanism so far described is capable of maintaining the speed of the generating unit within reasonably close limits, but is not sufficiently sensitive to effect the accurate regulation of the generators, which, in an alternating-current power system, is required to maintain close frequency regulation or load distribution control. To obtain higher precision, each of the prime movers is provided with calibrating or response-adjusting means.

In the case of prime mover 21, these response-adjusting means are shown as comprising a tension spring 64 disposed to exert an upward pull upon lever 57. The magnitude of this pull may be adjusted by shifting the vertical position of a spring-securing member 66, illustrated in the form of a threaded rod which cooperates with the interiorly threaded gear wheel 67. Rotation of gear wheel 67 moves member 66 up or down to effect a change in tension of the spring.

It will be apparent that an increase in spring tension will tend to increase the speed at which governor 55 will maintain prime mover 21, while a decrease in tension will cause the prime mover to correspondingly lower its speed, the response characteristics of the governor being dependent upon the force which the flyball mechanism must overcome in effecting the closure of the input control valves.

To rotate gear wheel 67, a motor 69 is pro-

vided. This motor may be of any suitable type capable of reversible operation, and as shown, it comprises an armature winding 70 and a field winding made up of two separate oppositely wound sections r' and l' . Energization from a direct-current source of the armature through field winding r' causes the motor to rotate in a direction which tends to raise the speed and output of generating unit A, while energization of the motor through field winding l' causes it to rotate in a speed- and load-lowering direction.

The prime movers of units B, C and D are similarly provided with governor calibrating means which include tension springs controlled by adjusting motors 74, 75 and 76, respectively. These means operate in a manner comparable to that just explained for biasing member 64 and adjusting motor 69 of generating unit A.

To control the governor adjusting motors of the generating units any suitable means for selectively completing one or the other of two circuits, such as a frequency regulator 78 (Fig. 2) may be employed. Regulator 78 is illustrated as being of a well known speed-responsive centrifugal-element step-by-step operation type. The frequency change-responsive element 80 is driven by a synchronous motor 82 which is energized by the voltage acting in a main power circuit 34-35-36 to which the generating units are connected.

Element 80 is provided with flyball members 84 which are mechanically linked with a vertically movable member 85 in such manner that an increase in rotative speed of element 80 causes member 85 to move upwardly, while a decrease in speed permits of a downward movement. These movements are transmitted to a contact-carrying arm 87 which is pivoted at one end 88 and which carries at the other end contact members 90 and 91 spring-supported in the manner shown. A weight 93 exerts a downward force on arm 87 to oppose the upwardly acting force of member 85, while a dashpot damping element 95 is utilized to increase stability.

In cooperative relation with the movable contact members 90 and 91 are disposed contact members 96 and 97 which are carried by supporting arms 98 and 99, each of which is pivoted to the left-hand end in the manner shown. The right-hand ends of these arms are caused, by means of tension springs, to bear against cam members 101 and 102, respectively. These cam members are disposed to be continuously rotated, as by a motor 104, in such manner that the regulator contact members 96 and 97 move towards and away from each other at regularly spaced time intervals.

In operation of the regulator 78, normal frequency of the voltage acting in power circuit 34-35-36 rotates the motor 82 at such speed that arm 87 is maintained at the intermediate or neutral position illustrated in which contact elements 90 and 91 do not engage with elements 96 and 97. A decrease in frequency allows arm 87 to move downwardly to the position in which contact member 91 is caused to engage member 97 at regularly spaced time intervals, the duration of which engagement periods varies with the displacement from the neutral position of arm 87. Likewise, an increase in the frequency of the power circuit voltage causes member 87 to be raised to a position in which contact member 90 engages with the member 96 at regular time intervals.

Engagement of the pairs of regulator contacts

90-96 and 91-97, respectively, control the actuation of two load control relays L and R, which, when actuated to the closed contact position by energization of their operating windings, serve to energize one of the load-adjusting motors 69, 74, 75 or 76 associated with the generating units in the load-raising or load-lowering direction, respectively, in a manner to be further explained.

It will be apparent that regulators of types other than the frequency-responsive device 78 may also be utilized to control the actuation of load-control relays L and R, also that means for selectively assigning the relay control among a number of different regulators at the will of an operator may be utilized in well known manner. Such a combination is shown in the system of Figs. 1 and 2 as comprising a double-pole, double-throw switch 700 which, when closed to the left-hand position connects the load-control relay circuits with the frequency regulator 78, just described, and which when closed to the right-hand position, shifts the relay-actuating circuits to a second regulator represented at 714, which regulator may be of any one of a number of types well known in the art, such, for example, as a load regulator.

It will further be apparent that manually-operable push buttons may likewise be utilized to effect the relay control, in which case the load-adjusting impulses which are routed through the program-load controller of our invention for selective assignment among the several generating units in the power system may be supplied by an operator. Such manual control means may comprise a pair of push buttons ML and MR which, when respectively depressed, effect the actuation of load-control relays L and R.

As connected, these master-load-adjusting push buttons are effective at all times irrespective of the position of regulator-selecting switch 700. However, when it is desired that the station load be adjusted manually, the blades of switch 700 may be moved to the open position in which both of the regulators 78 and 714 are disconnected from the load-control relays. For such a condition, push buttons ML and MR comprise the only source of load-adjusting impulses so that manual control of station load may be satisfactorily effected.

In the explanation of the system of our invention which is to follow, it will be assumed that switch 700 is closed to the left-hand position in which frequency regulator 78 is connected with the load-control relay actuating windings. It will be appreciated, however, that, insofar as the operation of the program-load control system is concerned, the load-adjusting impulses can as well be supplied from the second regulator 714, or manually through the operation of the push buttons mentioned.

In order to obtain improved operating efficiency of generating units A, B, C and D, it is desired that the load distribution among them be regulated in some predetermined manner, rather than being allowed to assume a pro rata division, such as would result were the load-adjusting motors of all the units to be simultaneously subjected to load-changing impulses from the regulator 78. Thus, as the load demand upon the main power circuit to which the four generators are directly connected changes, and tends to cause the frequency to differ from the desired value, instead of permitting the regulator to effect changes in the output of all of the

generators to restore the frequency, it is desired that the regulator control only one of the units, and, after the output of this unit has been adjusted to a predetermined value, that the regulator control be suitably transferred to another of the units.

The control transfer system disclosed in the previously mentioned Patent No. 1,920,544, provides, as has been pointed out, means for transferring the control of the regulator from one to another of a plurality of generating units or other machines in accordance with a predetermined schedule, and is capable of effecting the load distribution control requirement outlined above in a system in which the prime movers are of the single control valve type. Our invention is directed to a system employing multi-control valve prime movers. Such a program-control system is shown, in Figs. 1 and 2, as comprising a motor-driven selector switch 106 connected intermediate the generating units A, B, C and D and the load-control means of which regulator 78 is representative.

Intermediate the selector switch 106 and the generating units controlled are disposed program-selecting switching means, diagrammatically illustrated in Fig. 1 in the form of twelve sequence receptacles designated by S1 to S12, inclusive, and a similar number of machine receptacles, the sequence receptacles being connected with the selector switch 106 of Fig. 2 in the manner shown.

Each of the generating units A, B, C and D is provided with a set of three machine receptacles, the three receptacles in each set respectively corresponding to the three input control valves of the prime mover. Thus, unit A is provided with receptacles Ap, As, and At associated with the primary, secondary and tertiary valves of turbine 21, respectively. Similarly, unit B is provided with receptacles Bp, Bs, and Bt; unit C with receptacles Cp, Cs and Ct, and unit D with receptacles Dp, Ds, and Dt.

The sequence and machine receptacles are interconnected by means of removable jumper connections of any suitable type, one preferred form of which is illustrated in Fig. 17. In Fig. 17, S designates one of the stationary sequence receptacle members which may comprise a block of insulating material 110 which carries a plurality of conductor terminals 111 communicating with contact-making clips 112 mounted in the insulating block. It will be understood that the control circuit conductors of the transfer system shown in Figs. 1 and 2 are joined with terminals 111. In Fig. 17, M similarly designates one of the machine receptacles which may be of a construction identical to that just described, its terminals being joined with the control circuit conductors leading to the turbine of the generating unit. While the receptacle members of Fig. 17 are shown as having nine terminals, the number called for by the system of Figs. 13-14, it will be understood that only four of these terminals will be used in the system of Figs. 1-2.

To establish the removable jumper connections, indicated in the system of Figs. 1 and 2 by the dotted lines, removable plug devices 114 and 115 are provided for insertion into receptacle members S and M. As shown, each device may comprise a block of insulating material 117 from which project a plurality of conducting material studs 118 which are disposed to fit snugly into the clip members 112 of the stationary receptacle when the plug assembly is inserted therein. Elec-

trical connections from studs 118 may be brought from the plug in the form of a flexible cord 120, which cord terminates at its other end in the second plug member designated in Fig. 17 as 115, which is provided with an equal number of contact studs symmetrically connected to those of the first mentioned plug. That is, the top studs of the two interconnected plugs are joined together, the second studs from the top of both similarly connected, etc. The flexible cord 120 thus comprises a plurality of separately insulated conductors, the two ends of each of which terminate in similarly positioned studs in the plug members.

The switching means just described are for program-selecting service and, as has been mentioned, are disclosed and claimed in the previously mentioned Patent No. 1,920,544.

For purposes of preliminary explanation of the program-load-control system depicted in Figs. 1 and 2, let it be assumed that the electrical connections indicated by the dotted lines drawn between the sequence and machine receptacles are established in the manner there shown, as by the use of interconnecting program members shown and described in connection with Fig. 17. When such connections are made, the particular program of transfer operations given by schedule a in the table of Fig. 6 will be followed.

In the table of Fig. 6, which sets forth nine different programs of regulator transfer for increasing load demand, the circle-enclosed numerals opposite each of the schedule-designating letters indicate the sequential ranges of output defined by the input-control-valve openings of generating units, A, B, C and D, which the regulator is caused to consecutively make effective as the combined load demand on all of the generating units is progressively increased from a minimum to a maximum. It will be understood that load demand changes in the load decreasing direction cause the sequences outlined in Fig. 6 to reverse themselves.

Initiation of transfer operations may, as is pointed out in the copending applications mentioned, be effected in any suitable manner by means responsive to the loading of each of the several generating units involved. In power systems involving multi-valve prime movers, it is found essential to utilize for this purpose contact-making mechanisms operated in accordance with the position of the prime mover input-control valves, rather than wattmetric contact-making means disposed in the output circuits of the generators, the latter method being wholly inadequate in a program-load control system for multi-valve turbines, since there is no definitely fixed relation between the output of the generator and the exact position of the prime mover input control valves, particularly when the steam pressure and vacuum is subject even to small variations.

As has been mentioned, and will be made more evident, those undesirable loading ranges of the turbines within which it is desired to prevent continuous operation are determined by the points of valve-opening, so that it is necessary that the transferring operations be accurately initiated in accordance with valve position. We have, accordingly, illustrated input-valve-operated contact mechanisms in the system shown in Figs. 1 and 2.

In the diagrammatic representation of Fig. 1, the valve-actuated contact members are shown in the form best suited to illustrate their functioning, the preferred manner of actual arrangement

in a practical system being shown by Figs. 7 to 12 inclusive, which will later be described. In the simplified representation of Fig. 1, a contact member is illustrated as being mounted on the movable member of each input control valve of each of the several prime movers, and, in cooperative relation with this contact member, two stationary members are shown as being positioned so that they will be selectively engaged by the first-named member as the valve is adjusted from the open to the closed position. Electrical connections are made from these contact members to the control circuits of transfer-operation effecting means.

Thus, in the case of generating unit A, contact members 125, 126 and 127 are shown as being mounted upon the movable elements of the primary, secondary and tertiary valves 48, 49 and 50, respectively. In cooperative relation with member 125 is disposed stationary contact members 129 and 130. Stationary contact members 131 and 132 are similarly disposed with respect to movable member 126 of the secondary valve, while members 133 and 134 are positioned to be engaged by contact member 127 of the tertiary valve.

As shown, the positioning of the stationary members is such that when the valves are in the minimum load or closed position illustrated, the movable contact members engage stationary members 129, 131, and 133, respectively, while when the valves successively approach the opened positions, the movable contact members carried thereby engage stationary members 130, 132 and 134, respectively. As will be more completely explained, in the preferred form of operative system mentioned, the points of equivalent contact engagement are adjustable in order that the valve positions at which the transfer operations will be initiated may be set most advantageously.

In a similar manner, primary, secondary, and tertiary valves of each of generating units B, C and D are provided with contact members, which, in the closed positions of the valves, engage stationary members suitably positioned in cooperative relation thereto, while in the open positions of the valves, a second set of stationary members is similarly engaged. In the diagram of Fig. 1, the showing of these valve-actuated contacts is the same for all units, so that the detailed description which has been made in connection with unit A is deemed sufficient for the remaining three units.

The motor-driven selector switch 106 is shown as comprising four parallel-operated contact-establishing devices which include conducting-material strips L1, R1, Bk1, and F1, respectively. Mounted in a row parallel to each conductor strip are a plurality of stationary contact points which are disposed to be selectively connected with the strip by means of a movable contact-making brush device provided with two separate, but electrically connected, engaging surfaces, one of which bears upon the strip and the other of which bears upon the contact points. These brush devices which are designated at 136, 137, 138 and 139 in the switch 106 of Fig. 2 are all carried by a bar of insulating material 141 which is mounted in a manner to permit movement along the length of the conductor strips and the associated rows of stationary contact points.

Movement of brush-carrying bar 141 is effected by rotation of a threaded shaft 143 which cooperates with an interiorly threaded bushing 144 carried by the bar. The shaft carries a gear

wheel 145 which is disposed to be rotated by a switch-operating motor 146.

One preferred form of mechanical construction for selector switch 106 is illustrated in Figs. 15 and 16. In Fig. 15, which is a plan view of the switch, a base 500 of insulating material carries the plurality of conducting-material strips 502, alongside each of which is mounted the rows of contact points 504. The threaded shaft 143 is mounted in suitable bearings 506 and arranged to be driven through gearing 145 by the operating motor 146.

The insulating-material bar 141, which carries the contact-making brush devices, is suitably attached to the interiorly threaded bushing 144, which transmits to the bar movements along the length of the conductor strips 502 effected by rotation of shaft 143.

Each of the brush devices comprises two separate engaging fingers 510, one of which bears upon the conductor strip and the other upon the associated row of contact points. Supporting these contact fingers is a metallic strip 511 bent in the shape shown in Fig. 16 which is attached to insulating material bar 141 by means of bolts 512, which pass through a slot 543 in member 511. Each finger is slipped over an upwardly projecting pin 513 and maintained in contact with member 511 by means of a compression spring 515 held in place by a cotter-pin-secured washer 516.

When thus arranged, each of the contact fingers 510 tends to bear downwardly upon the conducting surface below with a pressure which is independently maintained by the compression spring so that unevenness in either the conductor strip or the contact points will be compensated for. Connection with the conductor strips and contact points is made to the securing bolts 517 which project through the insulating-material base 500.

The usual limit switches 203 and 266 are provided for interruption of the motor circuit when the limit of switch movement in the forward and backward directions, respectively, is reached. As illustrated, these limit switches are carried by a strip of insulating material 519 in such a manner that an upwardly projecting member 520 will act to open the contact members thereof if the normal travel limits of brush-carrying bar 141 are exceeded.

To ensure proper parallel advancement of all of the contact-making brushes, an auxiliary guide rod 522 is provided to engage with a bushing 523 carried by the movable bar member 141 and disposed to slide along rod 522 in a manner to steady the movement thereof.

The number of contact points provided for selective connection with each of the conductor strips of the selector switch is determined by the maximum number of transfer operations which it is required that the program load control system effect when the total load demand on all of the generating units controlled changes from minimum to maximum, or to full capacity on all the machines. In the system of Figs. 1 and 2, it is desired that each of the four generating units have three distinct operating or load ranges, determined respectively by the opening of the primary, secondary and tertiary valves, which ranges are designated by the curves of Fig. 3. Hence, the transfer switch 106 should have twelve different active positions, one for each valve range of each of the four generating units.

As shown in Fig. 2 the switch is provided with an additional position, which is inactive and utilized for a purpose to be described. Accordingly, the switch shown in Fig. 2 is provided with 5 twelve active contact points in association with each of the conductor strips and one inactive point. The twelve active positions of the contact-making brushes carried by arm 141 are designated by the row of circle-enclosed numerals 1 to 12, inclusive, which appear just to the left of strip Bk_1 . While the switch shown in Fig. 15 has ten rows of contact points, the number called for by the system of Figs. 13 and 14; it will be understood that only four of these 10 rows are utilized in the system of Figs. 1 and 2.

Two of the selector switch conductor strips L_1 and R_1 are utilized for the purpose of routing the load-lowering and load-raising impulses, respectively, of the regulator 78 from one to another 15 of the generating units A, B, C, and D, while the other two conductor strips Bk_1 and F_1 are similarly utilized to respectively route the load-demand-decreasing or backward and the load-demand-increasing or forward control circuits for 20 the switch-operating motor 146 among the valve-actuated contacts of the generating units.

Switch-operating motor 146 may be of any suitable type capable of reversible operation and is illustrated as comprising an armature winding 30 147 and two oppositely wound field windings f' and b' . Energization from a direct-current source of the armature winding through field winding f' causes the motor to rotate in a forward direction to move the several brush members carried by member 141 of the switch upwardly, while energization of the motor through field winding b' moves the switch brush members in a downward or backward direction. In the system of 35 Figs. 1 and 2, energization of motor 146 in the forward and reverse directions is respectively controlled by means of relays F and Bk , which may be designated as transfer-control relays.

It will be observed that the actuation of load-raising control relay R connects, through a contact member Ra carried thereby, the conductor strip R_1 of selector switch 106 to positive control conductor 38. In a similar manner, actuation 40 of load-lowering relay L connects, through a contact member La , conducting strip L_1 of the switch to the positive control conductor.

To the stationary contact points associated with switch elements L_1 and R_1 are brought connections from the load-adjusting motors 69, 74, 45 75 and 76 of the four generating units, the load-raising connections being brought to the points associated with element R_1 and the load-lowering connections being similarly brought to the points associated with element L_1 . The load-lowering connections comprise the conductors designated by r_1 to r_{12} , inclusive, while the load-raising connections comprise conductors r_1 to r_{12} , inclusive.

The armature windings of the load-adjusting motors are connected to negative control conductor 40 in the manner shown, so that there may be selectively completed for any one of these motors an energizing circuit which extends from the positive control conductor, through the auxiliary relays shown in Fig. 2, the selector switch element L_1 or R_1 and the windings of the motor back to the negative control conductor.

The transfer control relays F and Bk , mentioned as controlling the operation of selector switch adjusting motor 146 in the forward or increasing-load-demand and reverse or decreas-

ing-load-demand directions, respectively, serve to complete, when in the actuated position, motor energizing circuits through contact members Fa and Ba . Energization of the actuated windings of these transfer-control relays is effected by the engagement of a set of valve-operated contact members of one of the generating units A, B, C, or D, selection of the particular set of members which will be effective being determined by the position of the selector switch which determines the connection of elements F_1 and Bk_1 with the associated contact points.

It will be observed that the movable contact members associated with the prime mover valves are all joined with the positive control conductor 15 38, and that the actuating windings of the transfer control relays F and Bk are connected, through certain auxiliary relay contacts to be particularized, to negative control conductor 40. To the stationary contact points respectively associated with selector switch conductor strips F_1 and Bk_1 are brought, by means of conductors f_1 to f_{12} and conductors b_2 to b_{12} , connections from the contact members associated with the prime mover valves.

Thus there may be selectively completed for either of these transfer-control relays an energizing circuit which extends from the positive control conductor, through a set of valve-actuated contacts, the selector switch element F_1 or 30 Bk_1 , and the winding of the transfer control relay, back to the negative control conductor.

To deenergize the regulator control circuit during transfer operations so that undesirable arcing at the transfer switch contacts may be prevented, 35 the contact members Bd and Fd are provided on the transfer-control relays Bk and F . It will be seen that actuation of either one of these relays, which occurs during a transfer operation, interrupts the energizing circuit for the generating 40 unit load-adjusting motor which might at the time be completed by action of the regulator 78.

In the arrangement of the auxiliary relays shown in Fig. 2, before a transfer operation can be effected it is necessary that the valve-actuated contacts of the generating unit then in control properly engage and, in addition, that the regulator simultaneously close its contacts to initiate a load change operation in the proper direction. It will be observed that the energizing 50 circuit for transfer control relay F , for example, can be completed only when a contact member Rm carried by load-control relay R is in the closed position, and similarly, that an energizing circuit for the actuating winding of transfer control relay Bk can be completed only when a similar contact member Lm carried by load control relay L is closed.

Once a transfer operation has been initiated, however, an opening of the regulator contacts 60 should not interrupt it, otherwise, the selector equipment might become stalled in an off-contact position. To ensure uninterrupted energization, the transfer control relays F and Bk are provided with self-locking contacts Fg and Bg , 65 which will be seen to bridge the interlocking contacts Rm and Lm of the load-control relays.

In order to ensure that only one of the transfer-control relays, F or Bk , can actuate at any one time, the energizing circuit of the operating 70 winding of each relay is completed through a normally closed contact member carried by the other relay, these members being shown in the system of Fig. 2 at Fe and Be . It will be evident that with this arrangement, when one of the relays is 75

actuated, it is impossible to energize the actuating coil of the other relay, so that a simultaneous actuation of both is effectively prevented.

In order to prevent load-adjusting impulses in both the load-raising and load-lowering directions from being simultaneously sent through the selector equipment to the generating units supervised, the load-control relays L and R are provided with an interlocking arrangement which permits only one of them to be actuated at any one time. As shown, the energizing circuit of the operating winding of each relay is completed through a normally-closed contact member carried by the other relay, these members being illustrated in Fig. 2 at 716 and 721. Thus when one of the relays is in the actuated position, it is impossible to energize the actuating coil of the other relay, so that a simultaneous actuation of both is effectively prevented.

Connections from the valve-operated contacts associated with the four generating units to the selector switch 106 are made, as before mentioned, through the conductors designated by f_1 to f_{12} and b_2 to b_{12} , inclusive, the conductors having the "f" designations being associated with the valve contacts which are in engagement when the valves are in the open position, while the conductors having the "b" designations being similarly joined with the contacts which are engaged when the prime mover valves are in the closed position. Consequently, the selector switch 106 can be operated in the forward or load-demand-increasing direction only when the proper set of contacts closes in response to a prime mover valve opening adjustment, while the switch can similarly be operated in the backward or load-demand-decreasing direction only when the proper set of contacts is closed in response to a valve closing operation.

It will be observed that each one of the sequence receptacles designated in Fig. 1 by S_1 to S_{12} , inclusive, receives four conductors, identified by b , f , r and l , with appropriate subscripts, which are connected with similarly positioned contact points associated with conductor strips B_{k1} , F_1 , R_1 and L_1 of selector switch 106. The arrangement is such that when the switch is in position 1, shown in Fig. 2, switch elements L_1 , R_1 , B_{k1} and F_1 will be joined with the four corresponding points of sequence receptacle S_1 . Shifting of the selector switch to position No. 2, effected by movement of brush-carrying arm 141 upwardly to the second horizontal row of contact points, similarly connects these four switch elements with sequence receptacle S_2 , further changes in switch position in the forward direction progressively connecting the switch elements with sequence receptacles S_3 to S_{12} , inclusive. Thus, the subscript of each sequence receptacle designation corresponds to the position of the selector switch in which the auxiliary relays are connected with that receptacle.

It has been pointed out that the circuits terminating in the sequence receptacles are continued by means of plug or jumper connections to the machine receptacles. The raise and lower adjusting circuits thus brought to the three machine receptacles associated with each of the generating units are paralleled and connected with the governor adjusting motor of that unit, thereby permitting the motor to be energized through any one of the three receptacles. Thus, in the case of generating unit A, the raise and lower motor leads 155 and 156 are connected with the two points shown at the right-hand end of each of receptacles Ap , As and At .

Receptacle Ap , as has been mentioned, is associated with primary valve 48 of unit A. As with secondary valve 49, and At with tertiary valve 50. The point at the extreme left of each one of these receptacles is arranged for connection with the stationary contact member positioned for engagement when the associated valve is in the closed position, while the second point from the left-hand end of each of these receptacles is similarly connected with the contact member which is engaged when the corresponding valve is in the open position.

In the system of Figs. 1 and 2, these connections from each of the three machine receptacles are taken through a switch, shown generally at 158, which is provided for a purpose to later be made evident and which will be termed a "skip" switch. For purposes of preliminary explanation, let it be assumed that all of the six blades of switch 158 are thrown to the downward position, 20 designated in Fig. 1 by x .

The three machine receptacles associated with each of generating units B, C and D are connected with the valve-actuated contacts of the unit in the same manner as that just outlined for unit A, and an identical connection of the governor-adjusting motors of these units is likewise represented. For the time being, it will be assumed that the skip switches 160, 161, and 162 associated with each of the three generating units 30 last named are also all closed to the downward position.

Operation of program-load-control system

The essential elements of the fundamental program-load-control system of our invention now having been generally described, attention may be directed to the manner in which this system operates.

As has been mentioned, the particular interconnection of machine and sequence receptacles indicated by the dotted lines in Fig. 1 is the set-up required to give schedule a of Fig. 6, which schedule is further detailed in the operation-explanation table of Fig. 19. Reference to Figs. 6 and 19 show schedule a to be as follows:

Assuming that all four of the generating units are operating at minimum capacity, the frequency regulator 78 is in control of the primary-valve-load range of unit A. An increase in power demand, by tending to lower the frequency of the power system, causes the regulator to open the primary valve of unit A. When the open position of the valve is attained, a transfer operation is effected to shift the regulator control to the primary-valve-load range of unit B. Continued increase in load demand causes the regulator to open this valve, thereby effecting a further transfer of regulator control to the primary-valve-load range of unit C. When the primary valve of unit C has been opened the regulator control is then transferred to the primary-valve-load range of unit D.

Opening of the primary-valve of unit D effects a transfer of regulator control to the secondary-valve-load range of unit A. Further load-demand increase assigns control to the secondary-valve-load range of unit B, thence to the secondary-valve-load range of unit C, the secondary-valve-load range of unit D, the tertiary-valve-load range of unit A, and thence successively to the tertiary-valve-load ranges of units B, C and D. For the condition last named, units A, B and C are all operating at full capacity and the out-

put of unit D is being controlled within the upper or tertiary valve range of its capacity.

A decrease in load demand on the power circuit will be seen to cause the transfer operations 5 to take place in a sequence which is exactly the reverse of the one just stated.

Before proceeding further, it may be pointed out that the characteristics of generating unit governors, already described, are such that when the frequency of the voltage in the power circuit supplied by the units is maintained within close limits, of the order maintained by frequency regulators of present commercial design, the output of any given unit will remain substantially constant unless the governor setting is changed. 15 Hence, those generating units which are not under regulator control will normally continue to be loaded at the particular value determined by the last adjustment of governor calibration, 20 changes in load demand being taken only by the unit acted upon by the regulator. Thus, the program of loading just outlined actually obtains in practice.

It may further be pointed out that the program-load-control system of our invention differs from the previously mentioned type of system in which the generating unit loads are rigidly maintained at fixed values in that, as will be more clearly seen presently, it allows the governing means of all of the units to at all times be free and completely responsive to rapid demand changes. Thus, a sudden change in power demand, which is too rapid to be followed by the regulator and load-adjusting means of one generating unit alone, will be distributed among all of the several units momentarily or for the time required by the regulator, in being influenced by the change, to appropriately adjust the governor setting of the particular unit which it then controls. 30 This adjustment having been completed, the generating unit under regulator control takes on the total load-demand change and thereby allows all of the remaining units to return to their former output values.

It will thus be recognized that, through the application of our improved system of control, the stability limits of an alternating-current system are not detrimentally affected, since the normal instantaneous responses of the governing 45 means of all of the generating units involved are allowed to remain completely effective.

For the originally assumed condition in which all of the generating units are operating at exceedingly low values of load, the selector switch 50 106 will be in position 1, as illustrated, which represents the limit of switch travel in the backward or load-diminishing direction.

Frequency regulator 78 now being in control of generating unit A, an increase in load demand 55 on power circuit 34-35-36, by tending to lower the frequency of the system, causes the regulator 78 by closing contacts 91-97 to complete an energizing circuit for load-control relay R, which circuit extends from positive control conductor 38, through the conductor 165, contact-carrying arm 87, and contact members 91-97 of the regulator, conductor 166, blade 705 of switch 700, conductor 706, contact member 716 of relay L, conductor 718, the actuating winding of relay R, and conductor 167 back to negative control conductor 40.

Relay R, in moving to the actuated position, completes a circuit for energizing load-adjusting motor 69 of generating unit A in the load-raising 60 direction. This circuit extends from positive

control conductor 38, through conductor 169, contact member Ra of relay R, conductor 170, contact member Fd of transfer-control relay F, conductor 171, conductor strip R1, contact brush 137 and the contact point engaged thereby of selector switch 106, conductor r1, sequence receptacle S1, jumper connection 173, machine receptacle Ap, conductor 155, the field and armature windings r' and 70 of load-adjusting motor 69, and conductors 175 and 176 back to negative control conductor 40. Thus energized, motor 69 adjusts the governor of prime mover 21 in the manner that the output of generating unit A is increased, the action being to open primary valve 48 of prime mover 21. 15

In a similar manner, a decrease in the load demand of the power circuit causes the regulator 78, by closing contact members 90-96, to complete an energizing circuit for load-control relay L, which circuit extends from positive control conductor 38, through conductor 165, regulator contact members 90-96, conductor 179, blade 710 of switch 700, conductor 711, the actuating winding of relay L, conductor 720, contact-member 721 of relay R, and conductor 167 back to negative control conductor 40. 20

Relay L, in moving to the actuated position, completes a circuit for energizing the load-adjusting motor of generating unit A in the load-lowering direction. This circuit extends from positive control conductor 38, through conductor 169, contact member La of the relay L, conductor 181, contact member Bd of transfer-control relay Bk, conductor 182, conductor strip L1, contact brush 136 and the contact point engaged thereby of selector switch 106, conductor l1, sequence receptacle S1, jumper connection 184, machine receptacle Ap, conductor 156, the field and armature windings l' and 70, motor 69, and conductors 175 and 176 back to negative control 30 conductor 40. Thus energized, motor 69 adjusts the governor of generating unit A in the load-lowering direction and tends to effect the closure of primary valve 48 of prime mover 21. 35

Assuming that the load demand on the main power circuit continues to increase, causing the opening of the primary valve of unit A, contact member 125, shown as being carried by the valve stem, engages member 130 to initiate a control-transfer operation by setting up an energizing 45 circuit for forward-transfer-control relay F, which circuit may be completed by actuation of load-control relay R. This circuit extends from positive control conductor 38, through conductor 186, contact members 125 and 130 actuated by primary valve 48 of unit A, conductor 187, blade 188 of skip switch 158, conductor 189, machine receptacle Ap, jumper connection 191, sequence receptacle S1, conductor f1, and the selector switch contact point connected thereto, 50 brush contact 139, and conducting strip F1 of selector switch 106, conductor 193, contact member Rm of relay R, closed during load-raising 55 impulses from regulator 78, conductors 194 and 195, the actuating winding of relay F, conductor 196, contact member Be of relay Bk, and conductors 197 and conductors 263 and 167 back to negative control conductor 40. 60

Thus energized, relay F actuates its contact members upwardly, locking itself in through 65 member F1, which bridges contact member Rm or relay R, and completing, through contact member Fa, a forward energizing circuit for selector switch-operating motor 146. This circuit extends from positive control conductor 38, 70

through conductor 200, relay contact member Fa, conductor 201, limit switch 203, conductor 204, field and armature windings f' and 147 of motor 146, and conductor 206 back to negative control conductor 40.

Thus energized, motor 146 rotates in the forward direction to move the brush-carrying arm 141 upwardly, or in the load-demand-increasing direction to position No. 2, energization of the 10 motor continuing until brush 139 leaves the stationary contact point of position No. 1, at which time the energizing circuit for transfer control relay F is interrupted and the motor is thus caused to stop. The dimensions of the brush 15 member and the stationary contact points on which it bears are, as reference to Figs. 15 and 16 will indicate, such that the transfer control relay energizing circuit is maintained until the switch has been shifted to the next succeeding 20 position when interruption takes place.

In the No. 2 position of the selector switch, the several conductor strips are in engagement with the second horizontal row of stationary contact points from the bottom of the switch, thereby causing the regulator and auxiliary relays to 25 be connected with sequence receptacle S2, which receptacle is associated with the primary valve of unit B.

Load changing impulses from the regulator 30 are now routed to governor-adjusting motor 74 of unit B, through circuits which include conductors r2 and l2. These circuits are so closely similar to those already traced for load-adjusting motor 69 of unit A, that no further description 35 of them will be made. In switch position No. 2, likewise, the transfer-control relays F and Bk are connected for energization by the engagement of the contact sets associated with the primary valve 210 of unit B.

Continued increase in load demand will, therefore, cause the regulator to effect a progressive opening of the primary valve of unit B, which, when opened, will initiate, by the engagement of contact members 212 and 213, another forward transfer operation. The energizing circuit thereby set up extends from positive control conductor 38, through conductor 215, contact members 212 and 213, conductor 217 and blade 218 of skip switch 160, conductor 219, 40 machine receptacle Bp, jumper connection 220, sequence receptacle S2, conductor l2 and selector switch contact point connected thereto, brush element 139, and conductor bar F1 of selector switch 106, and thence through the actuating 45 winding of transfer control relay F to negative control conductor 40 through a circuit which has already been traced.

Relay F acts in the manner already explained to energize motor 146 in the forward direction 50 and thus causes selector switch 106 to be moved to the next or No. 3 position in the load-demand-increasing direction. In this new position, the switch circuits are connected with sequence receptacle S3, thus shifting the control of the regulator to generating unit C and assigning the transfer initiating circuits to the contacts associated with primary valve 222 of unit C. The regulator now acts upon load adjusting motor 75 of unit C by completing one or the other of 55 two energizing circuits, which include conductors r3 and l3.

Further increase in load demand, when continued uninterruptedly, progressively effects the 60 openings of the primary valves 222 and 227 of units C and D, the secondary valves 49, 232, 227,

and 231 of units A, B, C and D, and the tertiary valves 50, 240, 244, and 248 of the four units, the transfer equipment being caused to advance from position 3 to position 4 upon the engagement of valve-actuated contact members 224— 5 225, from position 4 to 5 by contacts 228—229, and successively through the intervening positions to position 12 by action of the contact member sets tabulated under the individual control section of Fig. 19 for the forward direction. 10

Each of the several transfer operations thus involved in the load-demand-increasing or forward direction is carried out in a manner identical with that already described in detail for the change selector switch position No. 1 to No. 2 and from 15 No. 2 to No. 3, so that detailed tracing of the circuits utilized for the remaining operations is deemed unnecessary, it having been seen that for each position of the selector switch the regulator and transfer circuits are connected with 20 the sequence receptacle whose "S" designation bears a subscript corresponding to the number of that switch position.

In switch position No. 12, in which the regulator is in control of generating unit D and transfer 25 initiation is assigned to the contacts associated with tertiary valve 248 of that unit, it will be recognized that generating units A, B, and C are all completely loaded to full capacity, while generating unit D is being operated within its 30 tertiary-valve-load range. Thus, when the tertiary valve of unit D is completely opened the full capacity of all of the generating units will have been brought into action.

For such a condition, as has been pointed out, 35 it is desired that the regulator be disconnected from the unit to which its control is assigned so that further load-raising impulses will not be permitted to excessively increase the tension of the governor adjusting spring by rotating the governor motor beyond the normal operating limit. In the system of Figs. 1 and 2 the inactive set 40 of selector switch contact points before mentioned as corresponding to the extra or No. 13 switch position, are utilized for such disconnecting service.

When valve 248 of unit D opens to effect engagement of contact members 250 and 252, conductor l2 is positively energized to effect actuation of transfer-control relay F which advances 50 the selector switch from position No. 12 to position 13 in which the several contacting brushes are in engagement with the contact points shown at the extreme top of the switch designation in Fig. 2. Inasmuch as the load-adjusting circuits comprising conductor strips L1 and R1 are in this position of the selector switch, connected to blank contact points, the load-raising control of the 55 regulator has been disconnected from all of the generating units.

The selector switch remains in this inactive position until the regulator supplies a load-lowering impulse, at which time transfer-control-relay BK is actuated through a circuit which extends from positive-control conductor 38, through conductor 730, brush contact 138 in engagement, 60 in switch position 13, with the contact point connected with conductor 730, conductor strip BK' and thence through the actuating winding of relay BK to negative control conductor 40 through a circuit which has already been traced. Relay BK thus operates the switch in a backward direction to position No. 12, which is an active one, as 65 has been seen.

The transfer equipment will remain in any one

of the several positions as long as the load fluctuations do not cause the generating unit under regulator control to change its output beyond the limits of the range of adjustment of the input control valve to whose contacts the transfer initiation is assigned.

The transfer operations resulting from a continuous increase in load demand from minimum to maximum capacity of all of the generating units having been described, attention may now be directed to the operations which result from a continuous change in demand in the opposite or decreasing-load direction. As before, the receptacle interconnections for schedule *a* of Fig. 6 will be assumed to be effective. As will be observed, such transfer operations are caused to take place in a sequence which is the exact reverse of that explained above as applying to increasing load demand.

With the selector switch 106 in position No. 12, load-adjusting impulses from the regulator 78 are transmitted to governor calibrating motor 76 of generating unit D, through circuits which include conductors *r*12 and *l*12 while transfer initiation is under the control of the contacts carried by the tertiary valve of this unit, as has been mentioned. Consequently, a decrease in load demand which causes tertiary valve 248 to move to the closed position initiates, by engagement of contact members 250—251, a transfer operation in the backward or load-lowering direction.

The circuit thereby set up, which energizes the backward transfer-control relay *Bk*, may be traced from positive control conductor 38, through conductor 253, contact members 250—251, conductor 254, blade 255 of skip switch 162, conductor 256, machine receptacle *Dt*, jumper connection 257, sequence receptacle *S*12, conductor *b*12 and the selector switch contact point connected thereto, contact brush 138 and conductor strip *Bk*1 of selector switch 106, conductor 259, contact member *Lm* of load-control relay *L*, closed when regulator 78 furnishes a load-lowering impulse, conductor 260, the winding of relay *Bk*, conductor 261, contact member *Fe* of transfer control relay *F*, and conductors 263 and 167 back to negative control conductor 40.

Thus energized, transfer control relay *Bk* actuates its contact members upwardly, completing through member *Ba* an energizing circuit for selector switch motor 146. This circuit extends from positive control conductor 38, through conductor 200, contact *Ba* of relay *Bk*, conductor 265, a limit switch 266, conductor 267, the field and armature windings *b'* and 147 of motor 146 and conductor 206 back to negative control conductor 40.

Motor 146 now operates selector switch 106 in the backward direction, causing the contact-making brushes to move downwardly to position No. 11, the actuating circuit for transfer control relay *Bk* being interrupted when contact brush 138 disengages from the No. 12 contact point. This interruption causes motor 146 to be de-energized so that it stops when the selector switch has reached position No. 11, in which position the regulator is in control of generating unit C and the transfer initiation is assigned to the tertiary valve 244 of this unit.

Further decrease in load demand, when continued uninterruptedly, progressively effects the closures of the tertiary valves of units C, B and A, the secondary valves of units D, C, B, and A, and the primary valves of units D, C, B, and A, the selector equipment being caused to shift from

position 11 to position 10 upon the engagement of valve-actuated contact members 245—270, from position 10 to 9 by contacts 241—281, and successively through the intervening positions to position 1 by action of the contact-member sets tabulated under the individual control section of Fig. 19 for the backward direction.

Each of the several transfer operations thus involved in the load-demand-decreasing or backward direction is carried out in a manner identical with that already described in detail for the change from selector switch position 12 to 11, so that a detailed tracing of the circuits utilized for the remaining operations is deemed unnecessary.

When the selector switch 106 has thus been returned to position No. 1 the regulator is again in control of generating unit A, and the transfer initiating circuits are controllable by primary valve 48 of this unit. For this condition, generating units B, C and D are all operating at minimum load, while unit A is operating within the primary-valve range.

Further decrease in load to an extent which closes valve 48 is prevented from initiating a further transfer operation, since no connection between sequence receptacle *S*1 and No. 1 contact point associated with selector switch element *Bk*1 is provided, the limit of transfer operations in the load-lowering or backward direction having already been reached and the generating units being in a condition in which their combined minimum output is already obtainable.

It will be observed that in tracing the detailed operations of the program-load-control system from a condition of minimum load demand progressively to a condition of maximum output of all of the generating units supervised, and then progressively back to the original condition of minimum load demand, all of the positions in the loading program have been examined. While in actual practice, load demand fluctuations will seldom occur in such a progressive manner as the one assumed, a more or less non-uniform or recurring type of load change being most frequently encountered, it will be understood that, regardless of the nature of the load variation, the transfer system of our invention will effectively function to route the load increments progressively among the generating units supervised in accordance with the particular program which has been set up by the interconnections of the sequence and machine receptacles.

In a system of the type under consideration, should the control machines get out of step with the selector switch, such as by failure of one of them to properly initiate a control transfer operation it is necessary, before normal operating conditions can be resumed, to synchronize the selector switch with the machine loading conditions, or in a system of the type shown in Figs. 1 and 2, with the valve positions of the generating-unit prime movers. A solution for this particular problem is given in Patent No. 1,907,517, in which resetting means are provided whereby the selector switch may be reset to any one of the several positions within its complete operating range.

Such means are shown in Fig. 2 in the form of manually operable push buttons 300 and 301 connected in the energizing circuit of the forward and backward transfer control relays, respectively. When it is desired that the position of the selector switch be reset or adjusted at the

will of an operator, one or the other of the push buttons may be depressed.

Thus, the operation of push button 300 completes an energizing circuit for transfer control relay F which extends from positive control conductor 38, through conductor 303, the push button 300, conductor 195, the winding of relay F, conductor 196, contact member Be of transfer control relay Bk, and conductors 197, 263 and 167 back to negative control conductor 40. Relay F may thus be maintained in the actuated position for as long a period as is desired, so that the energizing circuit for running motor 146 in the forward direction may be maintained until the necessary shift in position of selector switch 106 in the load demand increasing direction is obtained.

Similarly, a depression of push button 301 energizes transfer control relay Bk through a circuit which may be traced from positive control conductor 38, through conductor 303, the push button 301, conductor 260, the winding of relay Bk, conductor 261, contact member Fe of transfer control relay F, and conductors 263 and 167 back to negative control conductor 40. Thus relay Bk may be actuated to complete an energizing circuit for motor 146 which runs it in the backward direction to shift the position of selector switch 106 in the load demand decreasing direction.

Selection of transfer schedule

It has already been pointed out that in accordance with the teachings of copending application, Serial No. 606,158, previously mentioned, a plurality of transfer sequence programs or schedules are available in a program-load-control system of the type under consideration by changing the interconnections of the sequence and machine receptacles. One preferred form of interconnecting means has already been described in connection with Fig. 17 of this application.

It has been pointed out that when these connections are established in the manner shown by the dotted lines in Fig. 1, the program of transfer operations which the system of Figs. 1 and 2 will effect is that given by schedule *a* in the table of Fig. 6, which schedule has already been explained in detail. Through the use of the program-selecting switching means mentioned, the sequence and machine receptacles may be connected in other manners, so that additional schedules, such as are identified by *b*, *c*, *d*, *e*, *f*, *g*, *h* and *i* in the table of Fig. 6, are available when the receptacles shown in Fig. 1 are interconnected in the manner indicated in the last group of columns of the table of Fig. 6. In these columns, the two receptacle designations in each of the squares indicate an interconnection of the receptacle members identified by those designations.

It will be seen that to set up schedule *b*, for example, receptacle S1 is connected with Ap, S2 with Bp, S3 with As, S4 with Bs, S5 with Cp, S6 with Dp, S7 with Cs, S8 with Ds, S9 with At, S10 with Bt, S11 with Ct and S12 with Dt. As indicated in the table, this schedule provides that, for increasing load demand, the regulator is first in control of the primary valve of unit A, then the primary of unit B, the secondary of unit A, the secondary of unit B, the primary of unit C, the primary of unit D, the secondary of unit C, the secondary of unit D, the tertiary of

unit A, the tertiary of unit B, the tertiary of unit C, and finally the tertiary valve of unit D.

It will be recognized that this program selection feature very greatly broadens the usefulness of a program control system, it making for almost unlimited flexibility. Thus, in connection with the supervision of program-load control of generating systems involving multi-control valve steam turbines, it is particularly useful in that it permits the sequence which results in most efficient operation to be maintained.

It has been mentioned in an earlier portion of this specification that multi-input control valve prime movers of the steam turbine type particularly, present special requirements in the way of supervision by a program-load-control system. Such special requirements arise from the fact that as each additional control valve is opened, there is an abrupt change in heat rate and hence in the heat consumption, which changes have a direct bearing upon the operating economy of the generating unit. The curves of Fig. 3, which are characteristic of a typical three-valve turbine generating unit of the type shown in the system of Figs. 1 and 2 already described, illustrate graphically what these special requirements are.

The curves of Fig. 3 are representative of a well known type of steam turbine which is widely applied to large capacity installations and particularly to power generating stations. In this type of turbine, the steam consumption within the secondary valve range increases faster than within the primary valve range, and the consumption within the tertiary valve range increases faster than within the secondary valve range.

In Fig. 3, curve 350 indicates the heat consumption of the turbine throughout its total output range, while curve 352 indicates the corresponding heat rate. It will be observed that within the primary valve range, the slope of curve 350 is minimum and of a substantially constant value. As the secondary valve starts to open, the consumption very rapidly rises until sufficient steam is admitted to contribute driving force to the turbine. When the secondary jets have thus become effective, further opening of the secondary valve causes the heat consumption to increase at a constant rate which is somewhat faster than within the primary valve range, as is indicated. Similarly, as the tertiary valve starts to open, the heat consumption very rapidly increases until the tertiary steam jets become effective, and from that point, the total heat consumption of the turbine again increases at a constant rate which is somewhat higher than within the secondary valve range.

On the basis of curve 350, the heat rate curve of the turbine will have the general form indicated at 352 in Fig. 3. Because of the "wire drawing" effect which is present at the start of opening of the turbine valves and the fact that the very small quantity of steam initially admitted by the valve is ineffective in driving the turbine, as before explained, the heat rate very abruptly rises upon the opening of each additional valve, as is indicated by curve 352.

Operation of the turbine, therefore, within the load ranges in the immediate vicinity of the secondary and tertiary valve openings is undesirable for the reason that, in addition to the high heat rate there effective, the valve seat wear is excessive due to the wire drawing action of the steam passing through the narrow orifice. These

undesirable ranges are indicated in Fig. 3 by symbol z .

Reference to the curves of Fig. 3 further indicates that at low values of turbine loading, or 5 within the early portions of primary valve opening, both the heat rate and the heat consumption are relatively high. Hence, it is further desirable that continued operation of a generating unit within this particular range designated in Fig. 3 10 by z_1 shall also be avoided.

As has been already mentioned, the program load control system of our invention is capable of preventing continued operation of the generating units within all of these undesirable load ranges.

15 Reconsideration of the manner of initiating control transfer operations by valve-actuated contact closure, which has already been explained in connection with the program load control system of Figs. 1 and 2, will reveal that by suitably adjusting the points in the valve position ranges at which these contacts engage, the generating unit may be prevented from operating within predetermined regions of valve opening.

20 Referring specifically to generating unit A of Fig. 1, adjustment of primary valve contact members 125 and 130 for engagement slightly before the primary valve is fully open will cause a transfer operation to be effected at a point in the unit load range corresponding to 356 in Fig. 3. The regulator then being transferred to another unit, the loading of unit A will remain at value 356 until unit A is again assigned to regulator control.

25 Similarly, when unit A is operating within the secondary valve range, an engagement of contact members 126 and 132 in advance of the full opening of the secondary valve may be caused to effect a transfer operation at point 358 in Fig. 3. Unit A will, therefore, remain at this value of loading until again assigned to regulator control.

30 40 When operating in the tertiary valve range, adjustment of contact members 127 and 133, actuated by the tertiary valve, to close slightly before the valve closes may cause a transfer operation to be effected at point 360 in Fig. 3. It will thus be seen that the unit will be prevented from continuous operation within the range z limited by the load values 358 and 360.

35 In a similar manner, proper positioning of contact members 126 and 131 actuated by the secondary valve of unit A may be caused to effect a transfer operation before the secondary valve has completely closed or at a point corresponding to 362 in Fig. 3. It is thus also apparent that 45 operation of the generating unit within the range limited by unit loadings 356 and 362 in Fig. 3 may be effectively prevented by proper contact adjustment.

40 60 By corresponding adjustment of primary valve contact members 126 and 129 of unit A, the unit may be caused to effect a transfer operation when the loading has been decreased to a point corresponding to 364 in Fig. 3 so that continued operation within load ranges below this point designated by z_1 may be prevented.

65 70 75 It has been pointed out that to obtain the most advantageous schedule of loading, the efficiency characteristic of the several generating units supervised must be considered. In one preferred method of laying out the schedule of transfer operations we compare the heat consumption curves of all of the several turbine units involved in the power system, and, on the basis of this comparison, route the load-adjusting impulses among the valve ranges of the units in the manner that load increments will be taken on by

units having the lowest increase in heat consumption rate.

5 For a four-unit power system of the type shown in Figs. 1 and 2, the curves of Figs. 4 and 5 may be used to illustrate such a preferred method of schedule determination. In Fig. 4, the four heat consumption curves illustrated are assumed to respectively apply to generating units A, B, C and D of Fig. 1. It will be observed that the subscripts 1, 2 and 3 respectively identify portions 10 of each curve within the primary, secondary and tertiary valve ranges, respectively, while reference characters A, B, C and D to which these subscripts are applied identify the complete curves with the generating units. 15

Greatest economy is, as has been mentioned, to be obtained when load increments are taken on by units having the lowest increase in heat consumption. Consequently, the relative slopes of the several curve sections may be used to determine the sequence of regulator transfer. These relative slopes are more clearly shown in Fig. 5 in which each of the twelve lines there drawn is parallel to the consumption curve section of Fig. 4 with which its marking identifies it. On the basis of Fig. 5, the most desirable regulator control transfer schedule for increasing load demand is that given by the circle-enclosed numerals associated with the differently sloping lines of the figure. 30

35 This particular sequence is identified in the table of Fig. 6 by schedule i . It will be apparent that in laying out such a schedule, the only limitation in relative sequence is that the primary valve load range for each unit must precede the secondary, which in turn must precede the tertiary.

Skip switches

40 In a power station involving a plurality of generating units, it is not uncommon that repair work has to be done on some of the units, or for other reasons it may be necessary to shut down one or more of them. When supervised by a program-load-control system, it is, therefore, 45 highly desirable that means be provided whereby one or more of the generating units may be removed from service without interfering with the operation of the system in its supervision of the remaining units.

50 To attain this feature, we provide, in association with each one of the units, a skip switch which is connected in a manner that it permits the unit to be passed over or skipped in the program of transfer operations. In the system of 55 Figs. 1 and 2, these switches are shown at 158, 160, 161 and 162, as previously mentioned, for generating units A, B, C, and D, respectively.

55 60 Each of these switches is represented in the form of a six-pole double-throw knife switch combination, a pair of poles being associated with the contact members actuated by each of the input control valves of the prime mover. Thus in the case of switch 158 for generating unit A, the pair of poles at the left are connected with 65 the primary valve contacts of prime mover 21, the middle pair of poles to the secondary valve contacts, and the pair of poles at the right to the tertiary valve contacts.

65 70 75 When closed to the downward position designated by x , the generating unit is placed under normal control of the transfer system and operates in the manner already explained in detail. When the switch is closed upwardly to the position designated by s , which is the skip position,

the valve-actuated contacts are all short-circuited and thus react upon the transfer equipment in the same manner as if these contacts were maintained continuously closed.

5 It will be seen that the top studs of switch 158 are all joined with conductor 186 which is connected with the movable contact members actuated by the valve. Thus in the case of the secondary valve 49 and the middle pair of blades 10 310 and 311 of switch 158, when these blades are closed to position *s*, conductors *b*5 and *f*5, joined with these blades through sequence and machine receptacles S5 and A5, are connected with conductor 186, which will be recognized as having 15 the same effect upon the program load control system as if valve contact member 126 were simultaneously in engagement with contact members 131 and 132. It will be observed that the primary and tertiary valve contacts of unit A are 20 similarly short-circuited by action of the switch. Likewise, the switches 160, 161 and 162 are similarly connected with the valve-actuated contact members of units B, C and D, respectively, to effect a short-circuit thereof when closed to the 25 upward position.

Consequently, with the switch in the skip position, as the program controller reaches the unit in its sequence of operations, it receives an impulse to transfer the regulator control to another 30 unit, even if this other unit is more than one position removed from the initial assignment.

For purposes of further explanation, let it be assumed that it is desired to remove generating unit A from service, units B, C and D being maintained in normal operation. Switch 158 is, accordingly, closed upwardly to the skip position, while switches 160, 161 and 162 are closed downwardly to the program position designated by *x*. Assume that schedule *e* given in Fig. 6 has been 40 set up by suitable receptacle interconnections.

As the station takes on load, generating unit B will first be brought up to the capacity of its primary valve load range and the regulator control will then be transferred to unit A. In position No. 2 the selector switch connects the transfer control relays with the contacts of primary valve unit A, which contacts being short-circuited by the skip switch causes switch 106 to be moved to position No. 3 when the regulator provides the next-load-raising impulse. In accordance with schedule *e* of Fig. 6, position No. 3 corresponds to the secondary-valve load range of unit A. The contacts associated with this valve being short-circuited, another transfer operation in the load-raising direction is initiated. In moving to position No. 4, the selector switch transfers the regulator control to unit B and the transfer initiation to the secondary valve of this unit. Unit B being in active service, increases its output in the 60 normal manner.

In position No. 6 of the selector switch, according to schedule *e* of Fig. 6, regulator control is again returned to unit A, but the tertiary valve contacts of this unit being short-circuited by the skip switch, another transfer operation is immediately initiated carrying the selector switch to position No. 7, which assigns the regulator to the active generating unit C. From that point on the remaining transfer operations involve only active 65 units.

It is thus seen that the transfer equipment is enabled, by virtue of the skip switches, to pass over any one of the units which it is desired to take out of service and that the operation of the 70 program load control system is unaffected there-

by with respect to the remaining active units.

Should it be desired that the program load control system stop its operation at any one of the units, this feature may be obtained by placing the skip switch for that unit in the open position, 5 designated by *o* for switch 158 of Fig. 1. In the position *o*, it will be observed that the conductors which are utilized to energize the transfer control relays are completely disconnected from the valve-actuated contacts so that when the selector switch reaches a position corresponding to the unit for which the skip switch is opened, further transfer operations cannot be automatically initiated. Consequently the selector device will remain in that particular position until the skip 10 switch is again closed, or until manual adjusting as by means of push buttons 300 or 301, is effected.

It is thus evident that by virtue of the skip switches, three different operating conditions are 20 available. When in position *x*, supervision in the normal manner by the program load control system is effected for the generating unit with which the skip switch is associated. In position *o*, the program controller is caused to stop when it reaches the particular unit in its sequence of transfer operations, and, in position *s*, the program controller passes by the generating unit whenever it reaches it in the sequence of transfer operations, thereby supervising the remaining active units in the system in the normal manner. 25

Valve-position indicating lights

As a means for enabling an operator at some 30 remotely located point to determine the position of the input control valves of each of the generating unit prime movers, we have devised a system of indicating lights which provide a visual indication of the valve positions, and also of the load-changing impulses which act upon each of the 40 generating units under program-load-control supervision. In the system of Figs. 1 and 2, these indicating means are shown for generating units A, B, C and D in the form of lamp panelboards 45 315, 316, 317 and 318, respectively.

In each of these equipments, a lamp is provided for each of the prime mover valves and arranged to light when the unit is operating within the load range of that valve, and a lamp is also arranged to indicate the load-raising and the load-lowering impulses which are received by the governor-adjusting motor of the unit. The prime mover valve load ranges for a three-valve turbine generating unit and the corresponding ranges in which it is desired that each of the valve position-indicating lamps be illuminated are indicated in Fig. 3. 50 55

Considering equipment 315 for generating unit A, the primary, secondary and tertiary valve lamps are shown at 320, 321 and 322, respectively, while the raise and lower load-adjusting impulse lamps are shown at 324 and 325. 60

When the motor 69 of unit A is receiving a load-raising impulse, conductor 155 is energized, 65 as has been seen, by a positive potential so that lamp 324, connected between conductor 155 and negatively energized conductor 176, is caused to light whenever raise impulses are received by the motor. Similarly, lamp 325 connected between conductor 176 and conductor 156, which is positively energized upon the occasion of load-lowering impulses, will similarly light when load-lowering impulses are impressed upon motor 69. 70

To provide for the control of the valve posi- 75

tion lamps, two additional sets of contacts are provided for actuation in accordance with the position of the valve-actuated governor arm 57. These contacts are shown for unit A as comprising members 328—329 and 330—331, respectively. As indicated in Fig. 3, it is desired that the primary valve lamp 320 light continuously during the load range of this valve and be extinguished shortly after the secondary valve has started to open. To effect such control, the lamp energizing circuit is routed through contacts 328 and 329, which are shown as being engaged when the secondary valve is closed and which disengage shortly after the secondary valve starts to open. The energizing circuit for lamp 320 may thus be traced from positive control conductor 38, conductors 186 and 334, contact members 328 and 329, conductor 335, the lamp 320 and conductor 176 back to negative control conductor 40. In accordance with Fig. 3, it is desired that the secondary valve lamp 321 start to light shortly before the primary valve is completely opened and remain illuminated until after the tertiary valve starts to open, to thus include and extend slightly beyond both limits of the secondary valve range. To accomplish this, the set of contacts 330—331, shown as being actuated in accordance with the position of the governing arm 57, are utilized. In the position of the arm shown, in which all of the valves are closed, these contact members are disengaged. However, as the arm is raised in order to open the valves, contact member 330 engages member 331 just before the primary valve is completely opened and remains in engagement therewith until slightly after the secondary valve has completely opened. The energizing circuit for lamp 321 shown extends from positively energized conductor 334, through contact members 330 and 331, conductor 337, and the lamp 321, back to negatively energized conductor 176.

As indicated in Fig. 3, it is desired that the tertiary lamp 322 start to light just before the secondary valve is completely open and remain illuminated throughout the complete range of tertiary valve opening. To control this lamp, one of the sets of contacts utilized in connection with the transfer initiation circuits already examined may be utilized. In the case of generating unit A, this particular set comprises contact members 126 and 132 associated with the secondary valve. As has been pointed out, these contacts come into engagement at the particular position of the secondary valve at which it is desired that a transfer operation be initiated. This position corresponds, as has been pointed out, to the point indicated in Fig. 3 just prior to the complete opening of the secondary valve.

Conducting member 132 may be so disposed that engagement by member 126 will be continuous from the first contacting to the fully opened point in the tertiary valve range so that the desired control of the tertiary valve range lamp may satisfactorily be effected thereby. The energizing circuit shown for tertiary lamp 322 associated with generating unit A extends from positively energized conductor 186, through contact members 126 and 132, conductors 340 and 341, and the lamp 322, back to negatively energized conductor 176.

Through the system of indicating lamps just described, it is evident that a remotely situated operator can, by merely inspecting the light equipments associated with the several generating units in the system, advise himself as to the

load range within which each of the units is operating and also determine which of the units is being acted upon by the regulator.

By making proper adjustments of the indicating lamp control contacts, the ranges of lighting for these lamps may be adjusted to correspond to the active-load ranges designated in Fig. 3. It will be observed that when so adjusted, the primary and secondary lamp ranges overlap as do the secondary and tertiary ranges. Consequently, the simultaneous illumination of both the primary and secondary valve lamps indicates to the operator that the generating unit is operating within the immediate vicinity of secondary valve opening which is undesirable. Simultaneous lighting of the secondary and tertiary valve lamps likewise indicates a generating unit loading in the immediate vicinity of the tertiary valve opening which likewise is undesirable. The indicating lamp equipments, therefore, are especially useful in advising an operator of improper adjustments in the loading of the generating units supervised by the program load control system.

Transfer-initiating switch

The particular form of valve-operating mechanism shown in connection with the turbine-driven generating units illustrated in Fig. 1 is, as has been mentioned, of a highly simplified form chosen for purposes of effecting greater clarity in the explanation of the program-load-control system itself as affected by the valve-position-actuated contact members. In large capacity steam turbines of the type under consideration, it is customary to interpose between the flyball governor device or its equivalent and the input-control valves a system of oil-operated relays which serve to amplify the position-changing impulses originating in the governor to the extent required to operate the relatively heavy parts which must be used in the steam-input control valves of the turbine. A typical system of this type is shown in Fig. 7 in order to illustrate a preferred manner in which the transfer-operation initiating contacts may be combined into a single switch operated by the valve governor.

In Fig. 7, only the essential elements of the valve-control mechanism are illustrated, no attempt being made to show the complete turbine. The flyball governor device 370 is driven through suitable gearing from the shaft of the turbine, a worm gear which is mounted on this shaft being indicated at 371. Changes in speed of the turbine effect a vertical movement of arm 373 which is transmitted through a mechanical linkage to an oil-operated relay 375. Relay 375 amplifies the governing movements and transmits them through other mechanical linkages to a second and larger capacity relay 377 which is directly connected with the movable member 378 of the primary valve of the turbine. Actuated in accordance with the position of the primary valve rod 380 are two more oil relays 381 and 382 which respectively control the positions of the secondary and tertiary valve members 384 and 386.

The movable members of the three valves act to selectively admit steam from a common steam chest into the three separate sets of steam jets or nozzles within the turbine. The diagram of Fig. 7 shows the primary valve opened to full load, the secondary valve at the point of opening, and the tertiary valve firmly closed by oil pressure. Further upward movement of rod 380 opens the secondary valve and continued movement would open the tertiary valve.

To further clarify the explanation, the positions of the mechanical linkages which obtain when all of the valves are wide open are indicated by the dotted lines in Fig. 7, while the corresponding linkage positions when all valves are fully closed are indicated by the dot and dash lines.

All four of the oil relays mentioned are of similar construction, each being provided with a connection from a source of high-pressure oil designated in each case by "H. P. Oil", and with two oil outlet connections similarly designated by "Drain" for each of the relays.

Considering primary-valve relay 377, for example, a piston 384 is positioned inside of a cylinder 15 at the top and bottom of which oil may be admitted through ducts 386 and 387, respectively, to effect movement of the piston in a vertical direction. Connecting these ducts selectively with the source of high pressure oil 388 is a valve member, shown in the form of a plunger 390, which 20 may be moved up or down from the neutral position illustrated. This member is provided with three sections 392 which are grooved in a manner to permit the oil to flow from one duct to another 25 when the member is moved to bring the grooved section in contact with both duct chambers. Fig. 8, which is a section view of one of the grooved portions 392 of valve member 390, shows the manner in which these grooves are made in the cylindrical member.

In the case of each of the oil-operated relays, a downward movement of the control valve allows oil to be admitted from the high-pressure source to the region below the relay piston and thereby effects a movement of the piston in the upward direction, while, an upward displacement of the control valve admits high-pressure oil into the region above the piston, thereby moving it downwardly.

It will thus be seen that an increase in the speed of the turbine which moves the sleeve at the bottom of governor 370 upwardly acts upon oil relay 375 in a manner to cause the piston 395 thereof to move upwardly. This movement is transmitted through the mechanical linkages shown to primary valve relay 377, causing it to admit oil above piston 384 and move valve rod 380 downwardly tending to close the primary valve. Similarly, a decrease in turbine speed admits oil above the piston of governor relay 375 to move it downwardly, which movement acts upon primary valve relay 377 causing it to admit oil below piston 384 and move valve rod 380 upwardly, thereby causing opening of the turbine valves and admitting more steam.

The secondary and tertiary valve relays 381 and 382 are so operated in accordance with the position of rod member 380 that, as the primary valve 60 378 reaches the full load position, the secondary valve relay 381 will admit oil below piston 397 and effect an opening of secondary valve 384. When valve 384 is in the full open position, which corresponds to an upwardly shifted position of rod 65 380, tertiary valve relay 382 is similarly caused to admit oil below piston 398 to effect the upward movement of tertiary valve 386.

In Fig. 7, the governor calibrating or speed-and-load-changing equipment is shown as comprising a motor 400, which under the control of the regulator, adjusts the tension of a spring 402 which is mechanically linked with the governor-actuated arm 373 in the manner shown. It will be recognized that these two elements correspond 70 to motor 69 and spring 64 respectively associated

with generating unit A in the system of Figs. 1 and 2.

It will be understood that turbine governing mechanisms of the well known hydraulic-speed-responsive as well as other types function in a manner exactly comparable to that which has just been explained for the fly-ball speed responsive type in that the position of certain members in the valve-operating mechanism controlled thereby provide an accurate index to the positions of all of the input-control valves of the turbine.

Since the position of the central valve-operated rod 380 provides an accurate index to the positions of all three of the turbine valves, all of the contact members which, in the program-load-control system, are actuated by the several valves, may be combined into a single switch disposed to be operated in accordance with the position of member 380, which switch may be mounted in any 20 convenient location sufficiently near the turbine-governing mechanism to permit of direct mechanical connection. In practice this arrangement is found to possess many advantages over the more complicated method of attempting to 25 mount the contacts directly on the turbine valve stems in the manner shown in Fig. 1. Accordingly, in practicing our invention, we utilize such a common switch mechanism, one preferred form of which is illustrated at 405 in Fig. 7.

As shown, switch 405, illustrated as being of a cam operated type, is provided with a protruding operating arm 407 which may be mechanically connected with any one of the linkages of the valve-control mechanism which moves in accordance with the master valve stem 380. As shown, such connection is established by providing lever arm 409 with a bell-crank projection 410 to which switch arm 407 is connected by means of a suitable link member 411. When so interconnected, 40 switch arm 407 will be moved from the position designated by the dot and dash line 413 to the position designated by the dotted line 414 when the turbine valves are adjusted from the completely closed position for all valves, to the wide 45 open position. It will be recognized that this range of movement may be readily utilized to actuate the plurality of contact members required for each generating unit supervised by a program-load-control system.

The preferred form of transfer-initiating switch represented in end elevation at 405 in Fig. 7, comprises a base member 417 upon which the necessary contacts and cam operating means therefor are mounted, together with a protective sheet 55 metal case or cover 418 which completely encloses these contact mechanisms. Connections from the switch contacts may be brought out through a suitable conduit such as is represented at 419.

The mechanical construction of switch 405 is depicted in Figs. 9, 10 and 11. In Fig. 9, which is a view of the switch 405, with cover 418 cut away, and looking directly upon the base member 417 shown in Fig. 7, the externally protruding operating arm 407 is shown as being carried by a shaft 421 which is supported by ball bearings 424 and 425. A gear wheel 422 carried by operating-arm shaft 421, meshes with gear wheel 427 which 60 communicates movement to gear wheel 428 to drive through pinion 429, the main cam shaft 430 of the switch. Shaft 430 is supported by ball bearings 432 and 435 and carries a plurality of cam members, each of which selectively controls the 65 70 75

engagement of a set of contact members in accordance with the rotative position of the shaft.

As has been seen, each of the three-valve turbines illustrated in Fig. 1 requires, in the program-load-control system described, a total of eight sets of contact members—two sets for each of the three prime-mover valves for transfer-initiation control and two additional sets for valve-position-indicating lamp control. The valve-actuated switch 405 is, accordingly, provided with eight cam and contact member equipments which are designated in Fig. 9 by reference characters 441 to 448, inclusive.

Of these cam and contact equipments, assemblies 441, 442, 444 and 446 are of the normally-closed-contact variety shown in Fig. 10, while sets 443, 445, 447 and 448 are of the normally-open-contact variety depicted in Fig. 11. The manner in which these contact sets are electrically connected in the program-load-control circuits shown in Fig. 1 is indicated by the diagram of Fig. 12 which applies to the prime-mover valves of generating unit A. In Fig. 12 the several elements of the circuits shown in Fig. 1 are connected to the contact members of valve-operated switch 405, which are similarly designated in Figs. 9 and 12 by reference characters 441 to 448, inclusive.

The gear train already described, through which switch operating lever 407 rotates cam shaft 430, is utilized for the purpose of giving a greater range of rotative movement to the cam shaft than is obtainable by direct connection with the valve-operating mechanism, while the ball-bearing mountings for the shafts are utilized to reduce the torque required to operate the switch.

The transfer switch has been especially designed to provide high accuracy and a wide range of flexibility in adjustment of the actuating point of each of the cam-operated contact member sets. To attain these features, each of the contact assemblies is provided with two separate cams which may be independently positioned on the cam shaft.

Referring specifically to contact-member set 447, an end elevation view of which is shown in Fig. 11, these two cams are designated at 450 and 451. Each of the cams is loosely mounted on shaft 430 and secured in the desired position by means of a bolt or pin 453 which passes through the cams securing them to a rim member 455 which is keyed to the cam shaft by means of a key 457.

As illustrated in Fig. 11, each of the two cams may be of similar construction. One of them is provided with a plurality of holes 460 which match with an equal number of holes through the rim of the securing member 455, which holes are designated by the full line circles. The other of the cams is provided with a number of holes shown dotted differing by one from the number in the first-named cam and the securing rim member. In Fig. 11, fifteen full circle and fourteen dotted circle hole representations are illustrated.

For this combination, it is possible by suitably changing the position of the cam-securing pin to adjust the effective rotational position of the cams with respect to the cam shaft by the number of fractional portions of a complete revolution given by the product of 14 and 15 or 210. Hence, the adjustment range is exceedingly accurate.

Bearing upon each of the cam sets are a pair of cooperating rollers which communicate movement imparted thereto by the raised portions of the cams to a bell-crank arm which actuates the

contact members. All of the contact members and operating assemblies are mounted upon a common contact base 464 which is in the form of a strip of insulating material mounted parallel with the cam shaft and secured at its ends by means of brackets 466 and 467, respectively.

In the case of contact set assembly 447 shown in Fig. 11, the cooperating rollers are shown at 470 as being carried by a bracket 471 attached to member 472 which is pivoted at 473 to a member 474 directly mounted on the contact base 464. Integral with member 472 is a projecting bell-crank arm 475 to which is attached a resilient material conducting strip 476 on the end of which the movable contact member 132 is carried. Coil springs 478 and 479 are arranged to maintain the rollers 470 in contact with the cams, thereby maintaining movable contact member 132 in spaced relation with stationary member 126 which is mounted directly on the contact base 464.

Rotation of the cam shaft which brings the raised portion of the operating cams 450 and 451 into engagement with rollers 470, rotates arm 472 and contact carrying strip 476 in a counter-clockwise direction, in the view of Fig. 11, thereby causing contact member 132 to engage member 126. The construction just described for contact set assembly 447 shown in Fig. 11 also applies to assemblies 443, 445 and 448.

Assemblies 441, 442, 444 and 446 differ from that just described in respect to the arrangement of contact members. Instead of being disposed for engagement when the raised portion of the operating cams are in contact with the cooperating rollers, the contact members for these last-named assemblies are disposed for engagement when the rollers contact with the lowered portion of the operating cams and, for disengagement when the raised portion of the cams is contacted. This arrangement is shown in Fig. 10, which is a view of assembly 442.

Comparison of Figs. 10 and 11 will reveal that the only difference in construction of the two types of contact assemblies is in the manner of mounting the contacts. In the normally closed assembly shown in Fig. 10, the stationary contact member 125 is carried by a bracket 481 which is mounted on a contact base 464 in the manner shown. Rotation of the operating cams to bring the raised portions thereof into contact with the cooperating rollers thus moves contact member 129 out of engagement with member 125.

The switch just described has been found to represent a very satisfactory form of device for the service required, for in practice, it is a relatively simple matter to properly adjust the switch cams so that the desired contact operation in accordance with valve positions will be accurately effected. It will be understood that a switch of this or other equivalent type may be applied to any multi-valve steam turbine in which the position of a common operating member provides an accurate index to the positions of all of the several input control valves. Hence it is not restricted to application with the particular governing and valve-operating mechanism with which it has been illustrated in Fig. 7.

Parallel-pair control of generating units

In order to attain parallel-pair operation of the generating units controlled and thereby broaden the limits of maximum rate of total load change available, we have discovered that the following requirements must be met:

1. The regulator or other load-adjusting means

must simultaneously influence the load-adjusting motors of both of the generating units in each of the parallel-controlled combinations;

2. The regulator must be rendered ineffective 5 when the transfer schedule is set up other than to provide for sequential actuation of similar control valves of the paralleled units;

3. Transfer operations must be initiated by 10 whichever one of the parallel-controlled units whose valve adjustment first reaches the transfer point;

4. The backward transfer initiating circuits 15 must be routed among the valve-actuated contacts of the generating units in a staggered order with respect to the forward transfer initiating circuits to permit transfer operations to automatically proceed in both directions; and

5. A pro rata or balanced load division should 20 be maintained between the paralleled units throughout their complete range of valve adjustment.

Thus, to adapt the program-load-control system for parallel-pair operation of the generating units controlled, certain additions to the fundamental system described in connection with Figs. 25 1 and 2 must be made, the system depicted in Figs. 13 and 14 incorporating such necessary additions. As in the case of Figs. 1 and 2, the circuit conductors terminating at the right-hand 30 side of Fig. 13 are continued at the left-hand side of Fig. 14 in a manner that the apparatus illustrated in the two figures is interconnected.

It will be recognized that the complete system 35 shown in Figs. 13 and 14 is a duplicate of that given in Figs. 1 and 2, plus the additions to be described, this duplication not, however, including a showing of the valve-position-indicating light equipments 315, 316, 317 and 318 and associated valve-actuated contacts, or the skip 40 switches 158, 160, 161 and 162 shown in Fig. 1, such apparatus not being fundamental to parallel-pair control.

The system depicted in Figs. 13 and 14 is capable 45 of individual control of the four generating units in a manner which is identical with that explained for the system of Figs. 1 and 2, or of parallel-pair control, which, when effective, causes, in the particular arrangement shown, generating units A and B to form one pair and units C and D to form a second pair. To determine 50 which type of operation shall be effective, each pair of units is provided with a suitable control switch of a two-position type. These parallel-pair-operating control switches are illustrated, for the two pairs of units named, at 55 530 and 532, respectively.

When the blades of each switch, which is shown 60 in the form of a thirteen-pole double-throw knife blade device, are closed to the downward position designated by the circle enclosed *i*, the two generating units associated therewith are connected for individual control, while, when the blades are closed to the upward position designated by circle enclosed *p*, the two generating 65 units are connected for parallel-pair operation.

It will be observed that in Fig. 13, each of 70 the sequence receptacles S1 to S12, inclusive, and each of the associated machine receptacles is provided with nine contact points instead of four as illustrated in Fig. 1, the five additional points being required to accommodate the parallel-pair operation circuits to be described. Thus, each of the machine receptacles in Fig. 13 75 is joined with the selector switch 106' in Fig. 14 through the four conductors identified by *l*,

r, *f* and *b*, with appropriate subscripts, required for individual control of the generating units, plus the additional conductors illustrated. In the system of Figs. 13 and 14, all of the inter-connecting conductors between the two figures are shown as being run through four conduits 5 534, 535, 536 and 537.

To permit the regulator to simultaneously influence the load-adjusting motors of both of the paralleled generating units, the selector switch 10 106' is provided with the additional rows of contact points associated with conductor strips L2 and R2. Strips L2 and R2 are respectively connected with load-lowering and load raising governor-motor-control circuits which are respectively 15 controlled by load control relays L and R through contact members Lb and Rb. It will be observed that these members named are duplicates of contact members La and Ra, which control the circuits of which selector-switch conductor strips L1 and R1 form a part.

The contact points associated with conductor strips L2 and R2 of the selector switch are paralleled with the corresponding points in rows L1 and R1, respectively, while the contact-making 25 brushes 540 and 541 of these added assemblies are shifted ahead one position in the manner shown, so that the load-adjusting circuits of which conductor strips L2 and R2 respectively form a part, each communicate with the generating unit which is one step ahead in the sequence 30 schedule of the particular position which the selector switch occupies. It has been seen that this selector switch position determines the routing of load-adjusting circuits of which conductor strips L1 and R1 respectively form a part. By these means, the regulator 78 acts to simultaneously 35 control both generating units in each of the paralleled-pairs.

With reference to the mechanical construction 40 of the selector switch 106', which is completely shown in Figs. 15 and 16 already described, it will be seen that by loosening the holding bolts 512 which secure each of the contacting brush elements 511 to insulating bar 141, the 45 entire brush assembly may be shifted forwardly, or to the left in Figs. 15 and 16, so that the fingers 510 may be caused to engage the contact point which is one or more positions in advance of that engaged by the other brush devices when 50 secured in the particular positions illustrated in Fig. 15. Retightening of bolts 512 acts to secure the brush in the desired position such as is illustrated for devices 540 and 541 in Fig. 14.

In attaining the second-named requirement 55 for parallel-pair operation, means for rendering the regulator ineffective when the transfer schedule is not set up for sequential actuation of similar valves of paralleled units are shown in the form of additional rows of contact point on 60 the selector switch 106' with which are associated conductor strips M and N. Through these strips energization for the load-adjusting circuits is derived from the sequence and machine receptacles and the parallel-pair-operating 65 control switches.

The necessity for such a scheme will be apparent when it is considered that to maintain the load between two parallel control generating units in a pro rata or corresponding condition, 70 these units must at all times operate within corresponding valve-load ranges. Through the above-mentioned means, about to be more completely described, the program-load-control system will be rendered ineffective when the sched- 75

ules are improperly set up. In the table of Fig. 6, such schedules, which are improper for paralleled-pair operation, are identified by *g*, *h* and *i*, while schedules *a* to *f*, inclusive, conform with the 5 paralleled-pair operation requirement named.

One preferred form of mechanical construction for the sequence and machine receptacles shown in Fig. 13 is given in Fig. 17 in which, as has already been pointed out, *S* and *M* respectively 10 designate a sequence and a machine receptacle interconnected by plug members 114 and 115 which are joined through the flexible cord 120. Fig. 17 shows the nine point receptacles called for by the system of Figs. 13 and 14.

15 The added selector-switch assemblies *M* and *N* and the associated receptacle circuits, which are respectively identified by conductors *m*1 and *m*12 inclusive and conductors *n*2 to *n*12, inclusive, serve to control the energization of the load- 20 adjusting circuits by being interposed between the regulator actuated relays *L* and *R* and the positive control conductor 38. It will be observed that, while in the system of Figs. 1 and 2 contact members *L*_a and *R*_a of relays *L* and *R* 25 are joined with positive conductor 38 directly through a conductor 169, the corresponding contact members of relays *L* and *R* in the systems of Figs. 13 and 14 are joined with positive control conductor 38 through a circuit which includes 30 positively energized conductor 546 in Fig. 13, conductor 547, one of the interconnected sets of machine and sequence receptacles, one of the *m* designated conductors, conductor strip *M* of selector switch 106' and conductor 549.

35 Energization of the circuit last named is independent of the position of the parallel-pair operation control switches 530 and 532 of Fig. 13 so that it depends only upon the proper interconnection of the sequence and machine receptacles. 40 Energization of the load-adjusting circuits which include load control relay contacts *L*_b and *R*_b and selector switch contact strip *N* is similarly effected when the paralleled-pair operation control switches 530 and 532 are closed to the upward 45 or paralleled-pair operating position *p*.

When switch 530 is so closed upwardly, blade 552 connects conductor 554 through conductor 626, with positively energized conductor 547 through conductor 625, thereby permitting energization of the load-adjusting circuits for generating units *A* and *B* mentioned through one 50 of the sets of interconnected machine and sequence receptacles, an *n* designated conductor joined therewith, contact brush 556, conductor strip *N* of the selector switch 106', and conductor 558. It will be observed that brush device 556 55 is advanced one position ahead in the same manner as are brush devices 540 and 541 already described.

60 In this manner, since the load-adjusting circuits are carried through the machines and sequence receptacles, a proper setting up of the transfer schedule is required to render the regulator effective in adjusting the load of the paralleled-controlled units *A* and *B*. In a similar manner, blade 567 of switch 532 when closed to the upward position connects conductor 568 with positively energized conductor 547, thereby permitting energization of the load-adjusting circuits mentioned for generating units *C* and *D* 65 through one of the sets of interconnected machine and sequence receptacles, an *n* designated conductor connected thereto, selector switch conductor strip *N* and conductor 558.

70 In attaining the third named requirement for

paralleled-pair operation that the unit in the paralleled-controlled pair which first reaches the transfer position in its valve adjustment should initiate a transfer operation, we provide means whereby the valve-actuated contacts of the paralleled-units are connected in parallel when the control switches are closed upwardly to effect paralleled-pair operation. In the case of switch 530 for generating units *A* and *B*, blades 560 to 565 inclusive serve, when closed to the upward 10 position, to parallel all of the sets of valve-actuated contact members of generating unit *A* with the corresponding sets of contact members of unit *B*, while in the case of control switch 532, blades 570 to 575, inclusive, when closed upwardly 15 effect a similar paralleling of the valve-actuated contacts of generating units *C* and *D*.

To illustrate a typical circuit through which this is accomplished, blade 560 of control switch 20 530 acts to parallel primary valve contact members 129 and 294 of units *A* and *B* through a circuit which extends from member 129, through conductors 578 and 579, switch blade 560, and conductors 581 and 582 to contact member 294. It will be seen that each of the other switch 25 blades mentioned effects the desired parallel connection through a circuit which is closely similar to the one just traced.

Consequently, during parallel operation of each 30 of the pairs of generating units, the one which first adjusts its control valve to the transfer position will effect the desired transfer operation.

The fourth requirement for parallel-pair operation, that of routing the backward transfer initiating circuits among the valve-actuated contacts of the generating units in a staggered order 35 with respect to the forward transfer initiating circuits, must be met in order to permit the transfer equipment to automatically operate in the backward, as well as in the forward, direction 40 with but one arrangement of selector connections for the initiating circuits. In the system of Figs. 13 and 14, means for effecting this staggering are shown as comprising blades 600 to 45 605, inclusive, of parallel-pair-operation-control switch 530 and blades 606 to 611, inclusive, of control switch 532, these switch blades being disposed in electrical combination with the receptacle interconnections designated by conductors *bb*1 to *bb*11, inclusive, and other associated 50 circuits.

When control switches 530 and 532 are closed to the upward position *p*, there is completed for each set of backward transfer operation initiating contacts carried by the turbine valves, a circuit 55 which connects that contact set with the backward transfer initiating conductor from the selector switch 106' associated with the sequence receptacle which is one position behind that of the particular receptacle with which the contact 60 set is associated.

Thus in the case of contact members 250 and 65 251 actuated by the tertiary valve 248 of generating unit *D*, a shifting of the control switch 532 from the downward to the upward position disconnects, by means of switch blade 611, contact member 251 from conductor *bb*11, which is joined with sequence receptacle *S*12, and reconnects it by means of switch blade 608 with conductor *bb*11 70 of sequence receptacle *S*11. This newly set up circuit will be seen to extend from contact member 251, through conductor 613, machine and sequence receptacles *D*_t and *S*12, conductor *bb*11, sequence and machine receptacles *S*11 and *C*_t, conductor 615, switch blade 608, conductor 616, 75

and machine and sequence receptacles C₁ and S₁₁ to conductor b₁₁.

It will be observed that each of the remaining eleven sets of backward transfer operation initiating valve contacts is similarly rerouted in an inverted order to the sequence receptacles by means of the parallel pair operation control switch blades named.

10 Load-balancing scheme

The fifth requirement named for paralleled-pair operation, the provision of means for maintaining the loads between the parallel units divided in a balanced or pro rata manner, is attained through the provision of isolating relays intermediate the load-adjusting means of the two parallel controlled generating units and the regulator. These isolating relays are actuated by a load-unbalanced responsive element influenced by the paralleled generating units in such a manner that, whenever load unbalance occurs, the regulator control is removed from the machine leading in the direction of load change, it being restored again when the regulator acting on the other machine has restored the load to the balanced condition. In the system of Figs. 13 and 14, the isolating relays are illustrated at K and I in Fig. 14, while the unbalance-responsive element associated with generating units A and B is shown at UB1 and the element for units C and D at UB2 in Fig. 13.

The unbalance responsive elements may be of any suitable type capable of effecting selective closure of two sets of contact members as one or the other of the parallel controlled machines takes on more than its share of the total load output. As illustrated, element UB1 comprises two power-responsive devices 570 and 571, respectively, influenced by the output of generators 20 and 25 of units A and B.

Device 570 comprises a conducting material disc 573 which is subjected to sweeping magnetic fluxes impressed thereon by means of core members 575 and 576. This core member and disc assembly will be recognized as being the equivalent of that used in a well known type of induction watt-hour meter, each of the core members having a current and a voltage winding. The voltage windings 578 are energized directly by the generator voltage, while the current windings 579 are acted upon by the output current in two of the generator phase conductors through the medium of current transformers 580.

Device 571 of unbalance-responsive element UB1 is of identical construction to device 570 just described. It will be noted that each of these devices is so energized as to be responsive to the total power output of the generator, the well known two watt-meter method of connection for a three-phase circuit being shown.

The disc elements of devices 570 and 571 are mounted on a common shaft 582 in a manner that the two torques set up act in opposition. Consequently, when there is no difference between the two, as for example when the loadings of the two generators are balanced, no movement of shaft 582 will result. The shaft carries a contact member 583 which is normally biased in the mid position shown by means of springs 584 attached to the shaft.

In operation of element UB1, when the output of generating unit A is excessive with respect to that of generating unit B, contact member 583 is moved downwardly into engagement with the

set of studs shown below shaft 582, while, when the output of unit B is excessive with respect to that of unit A, the contact member is similarly moved upwardly into engagement with the set of contact studs shown above the shaft.

5

Unbalance-responsive element UB2 associated with generating units C and D is of identical construction to element UB1 just described. Hence, when the output of unit C becomes excessive with respect to that of unit D, contact member 587 of 10 the element is rotated downwardly into engagement with the set of contact studs shown below the element shaft, while when the output of unit D becomes excessive with respect to that of unit C, the contact member engages with the set of 15 studs shown above the shaft.

The unbalance responsive elements UB1 and UB2 supervise the actuation of the control-isolating relays K and I (Fig. 14) through circuits which include the machine and sequence receptacles and conductors i₁ to i₁₂, inclusive, connecting these receptacles with two rows of contact points associated with conductor strips I₁ and K₁ of selector switch 106'. Conductor strip I₁ is connected, by conductor 590, with the actuating 20 winding of isolating relay I, while conductor strip K₁ is similarly connected, through conductor 591, with the actuating relay of isolating relay K.

Each of the isolating relays is provided with two sets of normally closed contact members, one 30 of which is connected in the load-raising adjusting circuit of one of the paralleled-units and the other of which is connected in the load-lowering circuit of the other unit. These contact members, designated by I_a and I_b for relay I and K_a 35 and K_b for relay K, are thus connected in the two sets of load-adjusting circuits which are controlled by the load-control relays L and R. The schematic diagram of Fig. 18 more clearly illustrates this manner of combination.

In Fig. 18, only those portions of the governor-motor-control circuits which are involved by the fundamental scheme of load-balancing under consideration have been represented, the dotted sections of conductor indicating that additional 45 apparatus is, in the actual program-load-control system, interposed between the elements which these dotted sections are shown as connecting. The horizontally drawn lines at the top and bottom of the figure represent the positive and negative 50 control conductors 38 and 40, respectively, the windings of the two load-control relays, controlled by regulator 78, and the two isolating relays, controlled by unbalance-responsive element UB1, being respectively designated by R and L 55 and K and I.

The governor-calibrating motors of the two parallel-controlled units whose loads are to be balanced are indicated at 69 and 74, the load-raising field windings of these motors being designated by r' and r'' and the load-lowering windings by l' and l''. The contact members carried by each of the four relays named are designated in the same manner as in the diagram of Fig. 14.

It will be observed that isolating relay K has 65 one of its normally closed contact members K_a disposed in the load-raising control circuit of motor 69, while the other contact member K_b is disposed in the load-lowering circuit of motor 74. Similarly, isolating relay I has one of its 70 contact members I_a disposed in the load-lowering control circuit of motor 69 and the other contact member I_b is similarly connected in the load-raising circuit of motor 74.

In the operation of the load-balancing system 75

schematically depicted in Fig. 18, an excess load on the generating unit controlled by motor 69, by causing contact member 583 of unbalance-responsive element UB1 to engage with the contact studs shown below it, completes an energizing circuit for isolating relay K. In actuating, relay K opens, through contact members Ka and Kb, the load-raising circuit for motor 69 and the load-lowering circuit for the motor 74. Consequently, the regulator acts to readjust the load to the balanced condition, which, when restored allows element UB1 by biasing contact member 583 to the open position, to restore the regulator control to both units.

In a similar manner, when the generating unit controlled by motor 74 assumes an excess proportion of the load, element UB1 causes contact member 583 to engage with the studs shown above it, thereby effecting the actuation of isolating relay I to interrupt, through contact members Ia and Ib, the load-lowering control circuit for the motor 69 and the load-raising circuit for motor 74. For this condition, load-adjusting operations by regulator 78 when in the load-raising direction are routed only to the motor 69 and, when in the load-lowering direction only, to motor 74 so that the desired balance condition is thereby restored.

In the complete system depicted in Figs. 13 and 14, selector switch conductor strips I1 and K1 are respectively energized by one or the other of the paralleled-pair load unbalance-responsive elements UB1 or UB2 through contact brushes 594 and 595, which respectively bear upon contact points corresponding to, and one position in advance of, the selector switch position. These two rows of contact points are parallel-connected to communicate with the sequence receptacles through conductors i1 to i12, inclusive. They thus provide the two separate energizing circuits for relays I and K, which are completable upon the respective engagement of the contacts below and above the shaft of one of the unbalance-responsive elements UB1 or UB2. The desired division of load between the paralleled-controlled generating units is thus at all times maintained.

To prevent the simultaneous actuation of both of the isolating relays, the actuating coil circuit for each is routed through a normally closed contact member carried by the other. These contact members, shown at 597 and 598 for relays I and K, cause the actuation of either of the relays to interrupt the energizing circuit of the other.

55 Operation of complete parallel-pair control scheme

As an aid to explaining the operation of the complete system shown in Figs. 13 and 14, the table of Fig. 19 may be referred to. When the 60 parallel-pair-operation-control switches 530 and 532 are closed to the downward or individual-control position *i*, the system is the equivalent of that which has already been explained in connection with Figs. 1 and 2, which operation is 65 summarized by the individual control portion of the table of Fig. 19. When, however, control switches 530 and 532 are closed upwardly to position *p*, the generating units will be supervised in the manner indicated by the parallel-pair 70 control section of the table.

Thus, when selector switch 106' occupies position No. 1 as shown, regulator 78 simultaneously acts upon generating units A and B, the load-adjusting impulses being transmitted from relays R and L through circuits which respectively include

selector switch conductor strips R1 and L1 for unit A and strips R2 and L2 for unit B.

The load-raising circuit for unit A may thus be traced from positive control conductor 38, through conductors 546 and 547, machine and sequence receptacles Ap and S1, conductor m1, contact brush 616 and conductor strip M of selector switch, conductor 549, contact member Ra of load control relay A, conductor 170, contact member Fd of transfer-control relay F, conductor 618, contact member Ka of isolating relay K, conductor 619, conductor strip R1 and contact brush 137 of selector switch 106', conductor r1, sequence and machine receptacles S1 and Ap, conductor 155, field and armature windings r' 15 and 70 of load-adjusting motor 69, and conductor 176 back to negative control conductor 40.

The load-lowering circuit for unit A similarly extends from conductor 549, positively energized through the selector switch and receptacles in 20 the manner just stated, through contact member La of load-control relay L, conductor 181, contact member Bd of transfer control relay Bk, conductor 621, contact member Ia of isolating relay I, conductor 622, conductor strip L1, contact 25 brush 136 of selector switch 106', conductor 11, sequence and machine receptacles S1 and Ap, conductor 156, field and armature windings l' and 70 of load-adjusting motor 69, and conductor 176 back to negative control conductor 40. 30

The load-raising circuit for generating unit B extends, when the selector switch is in position No. 1, from positive control conductor 38, through conductors 546 and 547, conductor 625, blade 552 of control switch 530, conductor 626, machine and 35 sequence receptacles Bp and S2, conductor n2, contact brush 556 and conductor strip N of selector switch 106' conductors 558 and 628, contact member Rb of load-control relay R, conductor 629, contact member 631 of transfer-control 40 relay R, conductor 632, contact member Ib of isolating relay I, conductor 634, conductor strip R2 and contact brush 541 of selector switch 106', conductor r2, sequence and machine receptacles S2 and Bp, conductor 636, field and armature windings r' 45 and 638 of load-adjusting motor 74 and conductor 639 back to negative control conductor 40.

In a similar manner, the load-lowering circuit for unit B extends from conductor 558, positively 50 energized through the selector switch and receptacles as already detailed, conductor 628, contact member Lb of load control relay L, conductor 641, contact member 642 of transfer-control relay Bk, conductor 644, contact member Kb of isolating 55 relay K, conductor 645, conductor strip L2 and contact brush 540 of selector switch 106', conductor l2, sequence and machine receptacles S2 and Bp, conductor 647, field and armature windings l' 60 and 638 of load-adjusting motor 74, and conductor 639 back to negative control conductor 40.

For selector switch position No. 1, the control isolating relays K and I are actuated by the load unbalance responsive element UB1. When the loading of unit A becomes excessive with respect 65 to that of unit B, contact member 583 of this element is moved downwardly into engagement with the studs shown below it and thereby completes an energizing circuit for isolating relay K. This circuit extends from positive control conductor 38, through conductor 546, contact member 583 of element UB1, conductors 653 and 654, machine and sequence receptacles Bp and S2, conductor i2, brush contact 595 and conductor strip K1 of selector switch 106', conductor 591, 70 75

contact member 597 of isolating relay I, conductor 656, the actuating winding of isolating relay K, and conductor 657 back to negative control conductor 40.

5 Thus energized, relay K actuates its contact members upwardly interrupting, through member Ka, the hereinbefore traced load-raising circuit, for generating unit A, and, through contact member Kb, the load-lowering circuit for generating unit B. Further load-adjusting operations by the regulator are, therefore, caused to restore the load division between units A and B to the desired value, which, when it has been restored, permits unbalance-responsive element UB1 to move contact member 583 to the disengaged position. The isolating relay K is thus allowed to return to the unactuated position and the regulator control is again completely assigned to both of the generating units.

20 In a similar manner, when the loading of generating unit B becomes excessive with respect to that of unit A, unbalance-responsive element UB1 moves contact member 583 into engagement with the set of studs shown above it, thereby completing an energizing circuit for control isolating relay I. This circuit extends from positive control conductor 38, through conductor 546, contact member 583 of the element, conductors 660 and 661, machine and sequence receptacles Ap and S1, conductor f1, brush contact 594 and conductor strip 11 of selector switch 106', conductor 590, the actuating winding of relay I, conductor 663, contact member 598 of isolating relay K, and conductor 657 back to negative control conductor 40.

25 Relay I thus actuates its contact members upwardly interrupting through member Ib the load-raising control circuit for generating unit B and interrupting through member Ia the load-lowering circuit for unit A. Further adjustments by the regulator therefore tend to restore the load division between the two units to the desired value, and, when the restoration has been effected, isolating relay I is allowed to return to the unactuated position in which the regulator is again

40 in complete control of both units.

45 As is indicated in the table of Fig. 19, a transfer operation may be initiated by the primary valve of either generating units A or B, through the engagement of contact members 125-130 or 212-213, which are parallel-connected through blade 563 of control switch 530. Whichever one of the primary valves reaches the transfer point first in the course of its opening, thus initiates a forward transfer operation by completing an energizing circuit for relay F. This circuit extends from the positive control conductor 38, through conductor 546 or 215, contact members 125-130 or 212-213, conductor 650, machine and sequence receptacles Ap and S1, conductor f1, brush contact 139 and conductor strip F1 of selector switch 106', conductor 193, contact member Rm of load control relay R, closed when the relay supplies a load-raising impulse, conductor 194, the actuating winding of transfer-initiating relay F, conductor 196, contact member Be of transfer control relay Bk, and conductor 197, contact 721 of relay R and conductor 167 to negative control conductor 40.

50 Relay F, when moved to the actuated position, causes switch-operating motor 146 to rotate in a forward direction, thereby advancing the contacting brushes to position No. 2. When position No. 2 is reached, however, energization of the switch motor is not interrupted as in the case of individual control operation, for the mentioned paralleling of the two sets of contact mem-

bers actuated by the primary valves of units A and B causes conductor f2 to be positively energized upon contact engagement simultaneously with conductor f1. Hence, the motor continues to advance the transfer switch uninterruptedly from position No. 1 past position No. 2 to position No. 3, where interruption of the transfer control relay F is effected.

5 In position No. 3, the regulator acts upon units C and D, while the control isolating relays are actuated by load unbalance-responsive element UB2. Due to the exceedingly close similarity of the load-adjusting and load-balance maintaining circuits which are effective in position No. 3 to those which have already been in detail described for position No. 1, no detailed tracing of them will here be made.

10 In position No. 3, the regulator acts upon units C and D, while the control isolating relays are actuated by load unbalance-responsive element UB2. Due to the exceedingly close similarity of the load-adjusting and load-balance maintaining circuits which are effective in position No. 3 to those which have already been in detail described for position No. 1, no detailed tracing of them will here be made.

15 In position No. 3, the regulator acts upon units C and D, while the control isolating relays are actuated by load unbalance-responsive element UB2. Due to the exceedingly close similarity of the load-adjusting and load-balance maintaining circuits which are effective in position No. 3 to those which have already been in detail described for position No. 1, no detailed tracing of them will here be made.

20 A transfer operation may be initiated by the primary valve of either units C or D in the forward direction by contact members 224-225 or 228-229 and in the backward direction by members 224-229 or 228-290. These transfer initiating circuits are so similar to those which have been described for selector switch position No. 1 that no detailed tracing of them will be made. In accordance with schedule a of Fig. 6 upon which the operation explanation table of Fig. 19 is based, further increase in load demand effects a transfer operation to position No. 5, thence to 7, 9, and 11, the even-numbered selector switch positions being skipped over due to the two-position transfer which is effected by the paralleled-valve contact sets as already explained.

25 Assuming that the parallel pair control transfer operations have proceeded to bring selector switch to position No. 11 in which the regulator simultaneously controls generating units C and D, closure to the transfer initiating of the tertiary valves of either of these units sets up, by the engagement of contact members 245-270 or 250-251, an energizing circuit for transfer control relay Bk, which effects a transfer operation in the backward or load-demand-decreasing direction. This circuit extends from positive control conductor 38, through conductor 253, or conductor 670, contact members 250-251 or 245-270, conductor 613 to which contact members 270 and 251 are both joined, machine and sequence receptacles Dt and S12, conductor bb11, sequence and machine receptacles S11 and Dt, conductor 615, blade 608 of switch 532, conductor 616, machine and sequence receptacles Ct and S11, conductor b11, contact brush 138 and conductor strip Bk1 of selector switch 106', conductor 259, contact member Lm of load control relay closed when the regulator sets up a load-lowering impulse, conductor 260, the actuating winding of relay Bk, conductor 261, contact member Fe of transfer control relay F, and conductors 263 and 167 back to negative control conductor 40.

30 35 40 45 50 55 60 65 70 75 Relay Bk energizes switch-operating motor 146 in the backward direction, thereby causing it to shift the position of the switch from No. 11 to No. 10 where energization continuing, by virtue of the parallel contact connection already explained, the backward shift is continued to position No. 9.

From position No. 9 in which the regulator controls generating units A and B, closure of either of the tertiary valves of these units effects a further transfer operation in the backward direction to position No. 7. Continued decrease in total load demand progressively shifts the transfer to positions 5 and 3 and eventually back

to position No. 1. The circuits involved for these several positions are so closely similar to those already traced in detail that no further description of them is deemed necessary.

- 5 While the showing of schemes whereby the regulator may be caused to influence the generating units in groups instead of singly, in order to raise the available rate of total-load change, has been limited to parallel-pair operation of the units, 10 it will be apparent that if desired more than two units may be simultaneously influenced by extending the principles of paralleling just described.

Thus, three, four, or even larger numbers of 15 units may be parallel-controlled by making provision for causing the regulator to simultaneously influence the load-adjusting means of all of the units in each group, arranging the transfer-initiating circuits of the selector equipment for 20 control by the valve-actuated contacts of any one of these units, and properly setting up the system of load-balancing. If, for example, four units are to be parallel controlled, the total loading of one pair of them may be balanced against 25 the total loading of the remaining two, the load division between the two units in each of the pairs being maintained at a given value in the manner explained in detail.

The showing of the turbine generating units 30 in the system of Figs. 13 and 14 which has just been described, does not include the skip switch combination described in connection with the system of Fig. 1, nor the valve position indicating lamp equipments there also described. These 35 elements were purposely omitted from the parallel pair operation showing of Figs. 13 and 14 for the reason that they were not directly involved in the fundamental circuits necessitated by the parallel-pair control scheme. However, it will 40 be apparent to those skilled in the art that these elements may be combined with generating units whose control circuits are adapted for parallel-pair control operation. One preferred form of such combination is illustrated in Fig. 20.

45 In Fig. 20, which is a reproduction of generating unit A of Fig. 13 and the associated receptacle and other control circuits directly connected thereto, the skip switch 158 associated with generating unit A in the showing of Fig. 1 is illustrated 50 as being inserted between the machine receptacles Ap, As and At and the parallel pair operation control switch 530. In addition, the valve-position-indicating lamp equipment 315 shown in Fig. 1 and the necessary valve-actuated contacts 55 for controlling the lights have been shown connected with unit A in Fig. 20.

It will be apparent that the skip switch, when 60 so utilized in a system for parallel pair operation, functions in exactly the same manner as in a system wherein the generating units are individually controlled. For example, were it desired to isolate one of the units in a parallel controlled pair, the skip switch would be thrown upwardly to position S and by a short-circuiting of the contacts to be effected, would cause the transfer equipment to skip over all positions in which the pair of generating units, or which the unit in question forms a part, are involved. The parallel pair control switch provides, as has been indicated, for parallel connecting similar contact sets of the valves of both of the parallel units, so that the operation of either one or both of the skip switches associated with the units would effect the desired result.

75 The valve position indicating lights operate, as

has been pointed out, entirely independent of the parallel pair control circuits so that the showing of equipment 315 in Fig. 20 is an exact duplicate of the showing in Fig. 1, which has already been described.

5 While we have disclosed the improved program load control system of our invention in combination with an electrical power system involving four generating units controlled by a frequency regulator, it will be apparent that any number 10 of units can as successfully be adapted for supervision by it, and further, that an automatic regulator of the type illustrated is not an essential part of our inventive combination, it having been seen that the load-adjusting impulses, which the 15 system of our invention selectively routes among the several units, may be supplied from any source desired.

Likewise, while our invention has been disclosed in combination with generating units of 20 the steam turbine driven type, each of which turbines is provided with three separate control valves, it will be apparent that prime movers having any other number of control valves may also be successfully supervised. Nor is it necessary 25 that the units be similar either in capacity, or in the number of control valves with which they are provided. As will be apparent the several generating units supervised need not even be located in the same power station to permit 30 of control by our invention.

Although we have shown and described certain specific embodiments of our invention, we are fully aware that many modifications thereof are possible. Our invention, therefore, is not to be 35 restricted except insofar as is necessitated by the prior art and by the spirit of the appended claims.

We claim as our invention:

1. In a system comprising a power circuit having a plurality of electrical generators connected thereto, a fluid-operated prime mover of the multi-input-control valve type for driving each of said generators, a governor for controlling the valve openings for each prime mover, and a regulator responsive to a characteristic of said power circuit disposed to adjust the load settings of said governors, the combination of means for assigning the regulator control to one of said prime movers and for transferring it from one 50 to another when the valve-setting of the prime mover under control reaches given points, said means allowing normal responsiveness to sudden load-demand changes of all the prime mover governors and being disposed to selectively adjust the settings of the several governors to effect 55 changes in the total output of the prime movers, said output changes thus being progressively routed among the several prime movers in accordance with a predetermined program. 60

2. In a system comprising a power circuit having a plurality of electrical generators connected thereto, a fluid-operated prime mover of the multi-input-control valve type for driving each of said generators, a governor for controlling 65 the valve openings for each prime mover, and a regulator, responsive to a characteristic of said power circuit, disposed to adjust the load settings of the said governors, the combination of means for maintaining normal operation of the prime movers within predetermined ranges of valve opening, said means comprising a selector device for assigning the regulator control to one of said prime movers and for transferring it from one to another when the valve-setting of 70

the prime mover under control reaches a limit of one of said predetermined ranges, said means thus being disposed to cause selective adjustment of the said governors for effecting changes in the total output of the several prime movers, increments of said load changes being progressively routed among the prime movers in accordance with a predetermined program.

5. In combination, a system comprising a plurality of parallel-operated fluid-driven prime movers each of which has a plurality of input-control valves arranged for progressive opening and a governor for controlling said valves, electrical control circuits for adjusting the load-settings of the said governors, and means for preventing normal operation of the prime movers within those load ranges in which an additional control valve is just starting to open, said means comprising a selector device for assigning the control of said load-adjusting circuits to one of said prime movers and for transferring it from one to another when the valve-setting of the prime mover under control approaches the said additional valve-opening point, said means thus being disposed to permit selective adjustment of said governor settings in order to effect changes in the total output of the several prime movers in a manner that increments of combined-load change are progressively routed among the prime movers in accordance with a predetermined program.

6. In combination, a power circuit having a plurality of electrical generators connected thereto each of which is driven by a fluid-operated prime mover having a plurality of input-control valves and a governor for controlling the valve openings, a regulator, responsive to a characteristic of the power circuit, disposed to adjust the load setting of the prime-mover governors, and means for transferring the regulator control from one prime mover to another after a predetermined change in valve setting of the prime mover under control, said means acting to so route the regulator-control transfers that the settings of the prime mover valves will be varied in a predetermined sequence for changing power-circuit load conditions, complete maximum-to-minimum load change requiring a plurality of transfers in accordance with a predetermined program.

7. In combination, a power circuit having a plurality of electrical generators connected thereto, a fluid-operated prime mover for driving each of said generators, each of said prime movers having a plurality of input-control valves and governing means for controlling the valve openings, a regulator for adjusting the load settings of the governing means, and means for transferring the control of said regulator from the governing means of one prime mover to that of another in accordance with a given program as the power-circuit-load demand changes, said transfer means being disposed to operate when the valve of the prime mover then under regulator control in whose load range the prime mover is operating reaches predetermined points in its adjustment range.

8. In combination, a power circuit having a plurality of electrical generators connected thereto, a fluid-operated prime mover for driving each of said generators, each of said prime movers having a plurality of input-control valves and a governing mechanism for controlling the valve openings, load-control means for the prime movers, a selector device for assigning said load-control means to any one of the prime movers, and means comprising contact members disposed to engage during predetermined position ranges of each of said prime mover valves for operating said selector device, said last-named means comprising for each prime mover a multi-contact-set switch mechanism disposed to be operated by the governing mechanism of that prime mover.

9. In combination, an electrical generating system comprising a plurality of parallel-operated prime movers each of which has a plurality of input-control valves and a governing mechanism for controlling the valve openings, load-control means for the prime movers, a selector device for assigning said load-control means to any one of the prime movers, and means comprising contact members disposed to engage during predetermined position ranges of each of said prime mover valves, for operating said selector device, said last-named means, comprising for each prime mover, a switch mechanism disposed to be operated by the governing mechanism of that prime mover, said switch mechanism having a plurality of contact sets the engagement range of each of which may be adjusted to correspond to one of the said predetermined position ranges of one of the prime mover valves.

10. In combination, an electrical generating system comprising a plurality of parallel-operated prime movers each of which has a plurality of input-control valves and a governing mechanism for controlling the valve openings, load-control means for the prime movers, a selector device for assigning said load-control means to any one of the prime movers, and means comprising contact members disposed to engage during predetermined position ranges of each of said prime mover valves, for operating said selector device, said last-named means, comprising for each prime mover, a switch mechanism disposed to be operated by the governing mechanism of that prime mover, said switch mechanism having a plurality of contact sets the engagement range of each of which may be adjusted to correspond to one of the said predetermined position ranges of one of the prime mover valves.

11. In combination, an electrical generating system comprising a plurality of parallel-operated prime movers each of which has a plurality of input-control valves and a governing mechanism for controlling the valve openings, load-control means for the prime movers, a selector device for assigning said load-control means to any one of the prime movers, and means comprising contact members disposed to engage during predetermined position ranges of each of said prime mover valves, for operating said selector device, said last-named means, comprising for each prime mover, a switch mechanism disposed to be operated by the governing mechanism of that prime mover, said switch mechanism having a plurality of contact sets the engagement range of each of which may be adjusted to correspond to one of the said predetermined position ranges of one of the prime mover valves.

- assigning said load-control means to any one of the prime movers, and means, comprising contact members disposed to engage during predetermined position ranges of each of said prime mover valves, for operating said selector device, said last-named means comprising for each prime mover, a multi-contact-set switch mechanism operably connected with the governing mechanism of that prime mover, said connection being made with a valve-operating member of the governing mechanism whose position provides an index to the degree of opening of all of the valves of the prime mover.
12. In combination, an electrical generating system comprising a plurality of parallel-operated prime movers each of which has a plurality of input control valves and a governing mechanism for controlling the valve openings, load-adjusting means for acting upon the prime mover governors, a multi-circuit selector switch having a plurality of positions of a number as great as the sum of the individual valve-load ranges of all the prime movers, means for operating the switch from position to position, and means comprising contact members associated with and disposed to engage during predetermined position ranges of each of the prime mover valves, for controlling energization of the selector-switch operating means, two of the circuits of said selector switch being utilized to selectively assign the load-adjusting means to any one of the several prime movers in accordance with the switch position and two more of the selector-switch circuits being utilized to assign energization control for the said switch operating means to the contact members associated with the valve within whose load range the prime mover under load-control adjustment is being operated.
13. In combination, a plurality of parallel-operated electrical generators each of which is driven by a prime mover having a plurality of input-control valves and a governor for controlling the valve openings, a regulator for adjusting the governor load settings, a multi-circuit selector switch having a plurality of positions of a number as great as the sum of the individual valve-load ranges of all the prime movers, means for operating the switch from position to position, and means, comprising contact members actuated in accordance with the position of each of the prime-mover valves, for controlling energization of the selector-switch operating means, two of the circuits of said selector switch being disposed to selectively assign the regulator control to any one of the several prime movers, and two more of the selector-switch circuits being disposed to selectively assign energization control for the selector-switch operating means to the contact members associated with any one of the prime mover valves, said selector switch circuits being so arranged that each position of the switch is associated with the contact members of a different prime mover valve and with the governor of that prime mover, energization control of the selector-switch operating means thereby being assigned, for all positions of the switch, to the valve within whose load range the prime mover under regulator control is being operated.
14. In a system of program-load control for a plurality of parallel-operated machines comprising equipment for transferring in accordance with a predetermined schedule the control of a load-adjusting regulator from one machine to another upon the engagement of contact members associated with the machine under regulator control, each of said machines being provided with such contact members which are responsive to a condition of loading of the machine and which act to control the energization of transfer-operation-initiating circuits associated with the said transfer equipment, the combination of means for causing the transfer equipment to pass by any one of said machines in the sequence of transfer operations.
15. In a system of program-load control for a plurality of parallel-operated machines comprising equipment for transferring, in accordance with a predetermined schedule, the control of a load-adjusting regulator from one machine to another upon the engagement of contact members associated with the machine under regulator control, each of said machines being provided with such contact members which are responsive to a condition of loading of the machine and which act to control the energization of transfer-operation-initiating circuits associated with the said transfer equipment, the combination of means for causing the transfer equipment to pass by any one of said machines in the sequence of transfer operations, said means comprising a switch for each machine disposed in its closed or "skip" position to short circuit the said transfer-operation-initiating contact members associated with that machine.
16. In a system of program-load control for a plurality of parallel-operated machines comprising equipment for transferring, in accordance with a predetermined schedule, the control of a load-adjusting regulator from one machine to another upon the engagement of contact members associated with the machine under regulator control, each of said machines being provided with such contact members which are responsive to a condition of loading of the machine and which act to control the energization of transfer-operation-initiating circuits associated with the said transfer equipment, the combination of means for causing the transfer equipment to stop on position when it reaches any one of said machines in its sequence of transfer operations.
17. In a system of program-load control for a plurality of parallel-operated machines comprising equipment for transferring in accordance with a predetermined schedule the control of a load-adjusting regulator from one machine to another upon the engagement of contact members associated with the machine under regulator control, each of said machines being provided with such contact members which are responsive to a condition of loading of the machine and which act to control the energization of transfer-operation-initiating circuits associated with the said transfer equipment, the combination of means for causing the transfer equipment to stop on position when it reaches any one of said machines in its sequence of transfer operations, said means comprising a switch for each machine disposed in its open or "stop" position to interrupt the said transfer-operation-initiating circuits controlled by the contact members associated with that machine.
18. In a system of program-load control for a plurality of parallel-operated machines comprising equipment for transferring in accordance with a predetermined schedule the control of a load-adjusting regulator from one machine to another upon the engagement of contact members associated with the machine under regulator control, each of said machines being provided with such contact members which are responsive to a

- condition of loading of the machine and which act to control the energization of transfer operation initiating circuits associated with the said transfer equipment, the combination of a multi-pole three-position switch for each machine, disposed (1) in the first or "normal" position to connect the said transfer-operation-initiating circuits with the contact members associated with that machine to thereby permit normal functioning of the transfer equipment (2) in the second or "stop" position to interrupt said transfer-initiating circuits, to thereby cause the transfer equipment to stop on position when it reaches that machine in its sequence of transfer operations and (3) in the third or "skip" position to short circuit the transfer-operation initiating contact members associated with that machine to thereby cause the transfer equipment to pass by that machine in its sequence of transfer operations.
19. In a system comprising equipment for transferring in accordance with a predetermined program, the control of a load-adjusting regulator from one to another of a plurality of parallel-operated machines as the loading of the machine under control reaches given limits, at which limits contact means are disposed to set up operation-control circuits for the said selected equipment, the combination of means whereby the equipment-operation control will be rendered effective only when the regulator produces a control impulse in the proper direction simultaneous with the setting up of an equipment-operation control circuit.
20. In a system comprising a selector device for assigning the control of a load-adjusting regulator to any one of a plurality of parallel-operated machines, a pair of load-control relays disposed intermediate the regulator and the selector device, means for operating the selector device, a pair of transfer-control relays disposed to control the said operating means, and means for setting up actuating circuits for the transfer-control relays, the combination of means whereby said actuating circuits may be completed only when the regulator produces an impulse in the proper direction simultaneous with the setting up of the circuit, said means comprising a normally-open auxiliary contact member carried by each of the load-control relays, the said transfer-control-relay-actuating circuits being selectively routed through said contact members.
21. In a system comprising a selector device for assigning the control of a load-adjusting regulator to any one of a plurality of parallel-operated machines, a pair of load-control relays disposed intermediate the regulator and the selector device, means for operating the selector device, a pair of transfer-control relays disposed to control the said operating means, means for setting up actuating circuits for the transfer-control relays, and a normally-open auxiliary contact member carried by each of the load-control relays through which contact members the said transfer-control relay actuating circuits are selectively routed in a manner that completion thereof may be effected only when the regulator produces an impulse in the proper direction simultaneous with the setting up of the circuit, the combination of means whereby once a transfer-control relay has been energized it will so remain until the transfer-operation thus initiated has been completed, said means comprising a normally-open contact member carried by each of the transfer-control relays and parallel-connected with the said load-control relay auxiliary contact member associated with that transfer-control relay.
22. In a system comprising equipment for transferring in accordance with a predetermined program the control of a load-adjusting regulator from one to another of a plurality of parallel-operated machines as the loading of the machine under control reaches given limits, at which limits contact means are disposed to set up operation-control circuits for the said selector equipment, the combination of means whereby the regulator control will be interrupted when the said selector-equipment operation-control circuits are energized for effecting a transfer operation.
23. In a system comprising a selector device for assigning the control of a load-adjusting regulator to any one of a plurality of parallel-operated machines, a pair of load-control relays disposed intermediate the regulator and the selector device, means for operating the selector device, a pair of transfer-control relays disposed to control the said operating means, and means for setting up actuating circuits for the transfer-control relays, the combination of means whereby the control of the regulator will be interrupted when the selector device is effecting a transfer operation, said means comprising a normally-closed auxiliary contact member carried by each of the transfer-control relays, said contact members being respectively disposed intermediate the load-control relays and the said selector device.
24. In a system comprising a selector device for assigning the control of a load-adjusting regulator to any one of a plurality of parallel-operated machines, means for operating the selector device, and a pair of transfer-control relays disposed to control the said operating means, the combination of means for preventing simultaneous actuation of both of said relays.
25. In a system comprising a selector device for assigning the control of a load-adjusting regulator to any one of a plurality of parallel-operated machines, means for operating the selector device, a pair of transfer-control relays disposed to control the said operating means, and means for completing actuating circuits for the said relays, the combination of means for preventing simultaneous actuation of both relays, said means comprising a normally-closed auxiliary contact member carried by each relay through which the actuating circuit for the other relay is routed.
26. In a system comprising a selector device for assigning the control of a load-adjusting regulator to any one of a plurality of parallel-operated machines, and a pair of load-control relays disposed intermediate the regulator and the selector device, the combination of means for preventing simultaneous actuation of both of said relays.
27. In a system comprising a selector device for assigning the control of a load-adjusting regulator to any one of a plurality of parallel-operated machines, a pair of load-control relays disposed to transmit load-adjusting impulses through the selector switch, and actuating circuits controlled by the regulator for the said relays, the combination of means for preventing simultaneous actuation of both of said relays, said means comprising a normally-closed auxiliary contact member carried by each relay through which the actuating circuit for the other relay is routed.
28. In a system of program-load control for a plurality of machines in which the control of a load-adjusting regulator is transferred, in accord-

5 ance with a predetermined schedule, among the machines, said system comprising a selector switch having a plurality of positions each of which corresponds to a given machine, interposed 10 between the regulator and the machines, and means for operating the switch from position to position in response to predetermined conditions of machine loading, the combination of means for disconnecting the regulator from the machine 15 to which it is assigned with the selector switch occupying its last active position in the forward or total-machine-load-increasing direction when the regulator increases the loading of the said controlled machine to the full capacity value for that machine.

29. In a system of program-load control for a plurality of machines in which the control of a load-adjusting regulator is transferred, in accordance with a predetermined schedule, among the 20 machines, said system comprising a selector switch having a plurality of positions each of which corresponds to a given machine, interposed between the regulator and the machines, and means for operating the switch from position to 25 position in response to predetermined conditions of machine loading, the combination of means for disconnecting the regulator from the machine to which it is assigned with the selector switch occupying its last active position in the forward or 30 total-machine-load-increasing direction when the regulator increases the loading of the said controlled machine to the full capacity value for that machine, said means comprising an inactive position for said switch to which the switch is disposed to be operated when the said full-capacity machine loading is reached.

30. A system of program-load control for a plurality of parallel-operated machines comprising equipment, including a control routing device and machine-load-change responsive means associated therewith for transferring in accordance with a predetermined program the control of a load-adjusting regulator from one group of machines to another group upon predetermined 45 conditions of loading of the machines under regulator control.

31. A system of program-load control for a plurality of parallel-operated machines comprising equipment for transferring in accordance with a predetermined program the control of a load-adjusting regulator from one group of machines to another group upon the engagement of 50 contact members associated with either of the machines under regulator control, each of said machines being provided with such contact members which are responsive to a condition of loading of the machine.

32. A system of program-load control for a plurality of parallel-operated machines comprising equipment for transferring in accordance with a predetermined program the control of a load-adjusting regulator from one group of machines to another group upon the engagement of contact members associated with any one of the 65 machines under regulator control, each of said machines being provided with such contact members which are responsive to a condition of loading of the machine, and means for maintaining the load-division among the machines in each of 70 said simultaneously controlled groups at a pro rata or balanced value.

33. In a system of program-load control for a plurality of machines comprising equipment for transferring in accordance with a predetermined program the control of a load-adjusting

regulator among the machines, the combination of means for causing the regulator to influence the machines either singly or in pairs, said means comprising a two-position control switch associated with each set of two machines which are to be simultaneously controlled during parallel-pair operation.

34. In a system of program-load control for a plurality of machines comprising equipment for transferring in accordance with a predetermined program the control of a load-adjusting regulator from one pair of machines to another pair upon predetermined conditions of loading of the machines under regulator control, the combination of means for maintaining at a pro rata or balanced value the load-division between each of said pairs of simultaneously controlled machines throughout their complete range of load control.

35. In a system of program-load control for a plurality of machines comprising equipment for transferring in accordance with a predetermined program the control of a load-adjusting regulator from one pair of machines to another pair upon predetermined conditions of loading of the machines under control, the combination of means for maintaining at a pro rata or balanced value the load-division between each of said pairs of simultaneously controlled machines throughout their complete range of load control, said means comprising for each of the machine pairs, load-unbalance responsive means disposed to take said regulator control away from one of the machines when the ratio of paired-machine loadings departs from a given value.

36. In a system of program-load control for a plurality of machines comprising equipment for transferring in accordance with a predetermined program the control of a load-adjusting regulator from one pair of machines to another pair upon predetermined conditions of loading of the machines under regulator control, said regulator being disposed to simultaneously adjust the loading of both machines in each of the pairs to which its control is selectively assigned, the combination of load-unbalance responsive means associated with each of said pairs of machines and disposed to take the regulator control away from one of the machines in the pair when the load ratio of the paired machines departs from a given value, selection of control isolation being made in a manner that the regulator control of the other machine restores load apportionment between the pair to the desired ratio.

37. In a system of program-load control for a plurality of machines comprising equipment for transferring in accordance with a predetermined program the control of a load-adjusting regulator from one pair of machines to another pair upon predetermined conditions of machine loading, said regulator being disposed to simultaneously adjust the loading of both machines in each of the pairs to which its control is selectively assigned, the combination of a load-unbalance responsive element associated with each of said pairs of machines, a pair of control-isolating relays interposed between the regulator and the said transfer equipment, the load-adjusting impulses being routed through said control-isolating relays to the two machines in each of the said pairs to which the regulator control is selectively assigned, and means for causing the said load-unbalance responsive element of the machine pair assigned to regulator control to control the actuation of the said isolating relays.

38. In a system of program-load control for a

plurality of machines comprising equipment for transferring in accordance with a predetermined program the control of a load-adjusting regulator from one pair of machines to another pair upon 5 predetermined conditions of machine loading, said regulator being disposed to simultaneously adjust the loading of both machines in each of the pairs to which its control is selectively assigned, the combination of means for maintaining 10 at a pro rata or balanced value the load-division between each of said pairs of simultaneously controlled machines, said means comprising a load-unbalance responsive element associated with each of said machine pairs, a pair of isolating relays interposed between the regulator and the said transfer equipment in a manner that each relay interrupts the load-raising control of one machine and the load-lowering control of the other machine in the pair to which the regulator 15 control is assigned, and means for causing the load-unbalance responsive element of the said machine pair to which regulator control is assigned to actuate one or the other of said isolating relays when the load-division between said 20 two machines departs from a given value, relay actuation being made in a manner that regulator control of the unisolated machine restores load apportionment to the desired value.

39. In a program-load control system for a plurality of machines in which the control of a load-adjusting regulator is transferred, in accordance with a predetermined schedule, among the machines, said system comprising a multi-circuit selector switch, having a plurality of positions 30 each of which corresponds to a given machine, interposed between the regulator and the machines, the combination of means for causing the regulator to control the machines in pairs comprising duplicate control circuits for transmitting the load-adjusting impulses to circuits 35 associated with two adjacent positions of the selector switch, said circuits being disposed to respectively influence the two machines in the pair to which the regulator control is at any 40 time assigned.

40. In combination with a plurality of parallel-operated machines and a load-adjusting regulator for effecting the control thereof, a program-load-control system comprising a multi-circuit selector switch having a plurality of positions 50 each of which corresponds to a given machine disposed to transfer the regulator control among the machines, means for causing the regulator to influence the machines in pairs comprising a pair of duplicate control circuits for transmitting the load-adjusting impulses to machine circuits 55 associated with two adjacent positions of the selector switch, which machine circuits respectively influence the two machines in the pair to 60 which the regulator control is assigned, and means for effecting a two-position shift of the selector switch, when the loading of the controlled pair of machines reaches a given condition, to thereby transfer the regulator control to 65 another pair of machines.

41. In a program-load-control system for a plurality of machines in which the control of a load-adjusting regulator is transferred, in accordance with a predetermined schedule, from 70 one group of said machines to another group when the loading of the controlled machines reaches a given condition, the combination of means for causing any one of the machines in the controlled group whose loading first reaches 75 the said given condition to initiate a transfer of

regulator control to another of the machine groups.

42. In combination with a plurality of parallel-operated machines and a load-adjusting regulator for effecting the control thereof, a program-load-control system comprising selector equipment for assigning in accordance with a predetermined program the control of the regulator from one group of machines to another group, means for operating said selector equipment, contact members actuated in accordance with a condition of loading of each machine and means whereby the contact members of any machine in the controlled group are disposed to control the energization of the said selector equipment operating means. 15

43. In combination with a plurality of parallel-operated machines and a load-adjusting regulator for effecting the control thereof, a program-load-control system comprising selector equipment for assigning in accordance with a predetermined program the control of the regulator from one group of machines to another group, means for operating said selector equipment, contact members actuated in accordance with a condition of loading of each machine, and means whereby the contact members of any machine in the controlled group are disposed to control the energization of the said selector equipment operating means, said means comprising circuits for parallel-connecting the said contact-members 30 associated with the machines in each of the parallel-controlled groups.

44. In combination with a plurality of prime movers each of which has a plurality of input-control valves and a load-adjusting regulator for effecting the control of said prime movers, a program-load control system comprising selector equipment for assigning the regulator control among the prime movers, means for presetting the program of transfer operation to follow any 35 given prime-mover valve-load range sequence desired, means for causing the regulator to control the prime movers in groups, and means for rendering the regulator control effective only when the control transfer schedule is set up to 40 cause sequential actuation of similar valves of the prime movers in each of the parallel-controlled groups. 45

45. In a system of program-load control for a plurality of machines comprising equipment for transferring in accordance with a predetermined program the control of a load-adjusting regulator from one pair of machines to another pair upon the engagement of contact members associated with either of the two machines under simultaneous regulator control, each of said machines being provided with such contact members which are responsive to a condition of loading of the machine, the combination of means for causing the said transfer equipment to be automatically 50 operated in both the forward or load-demand increasing and backward or load-demand decreasing directions with but one connection combination of transfer initiating circuits of the system. 55

46. In a system of program-load control for a plurality of machines comprising equipment for transferring in accordance with a predetermined program the control of a load-adjusting regulator from one pair of machines to another pair upon the engagement of contact members associated with either of the two machines under simultaneous regulator control, each of said machines being provided with such contact members which are responsive to a condition of loading of the 70 machine. 75

machine, the combination of means for causing the said transfer equipment to be automatically operated in both the forward or load-demand increasing and backward or load-demand decreasing directions with but one connection combination of transfer initiating circuits of the system, each backward transfer-initiating circuit in the said connection combination being routed to the said control-transfer equipment one transfer-position behind the corresponding forward transfer-initiating circuit.

47. In combination, a system comprising a plurality of parallel-operated fluid-driven prime movers each of which has a plurality of input-control valves arranged for progressive actuation and a governor for controlling said valves, electrical control circuits for adjusting the load-settings of the said governors, and means for pre-

venting normal operation of the prime movers within those load ranges in which a valve is about to be completely closed, said means comprising a selector device for assigning the control of said load-adjusting circuits to one of said prime movers and for transferring it from one to another when the valve-setting of the prime-mover under control approaches the said complete valve-closing point, said means thus being disposed to permit selective adjustment of said governor settings in order to effect changes in the total output of the several prime movers in a manner that increments of combined-load change are progressively routed among the prime movers in accordance with a predetermined program. 5 10 15

ARNOLD P. HAYWARD.
THOMAS E. PURCELL.

CERTIFICATE OF CORRECTION.

Patent No. 1,984,187.

December 11, 1934.

ARNOLD P. HAYWARD, ET AL.

It is hereby certified that error appears in the printed specification of the above numbered patent requiring correction as follows: Page 13, first column, lines 35 and 36, strike out the words "copending application," Serial No. 606,158" and insert instead Patent No. 1,907,517; and page 21, first column, line 19, for "unbalanced" read unbalance; and that the said Letters Patent should be read with these corrections therein that the same may conform to the record of the case in the Patent Office.

Signed and sealed this 12th day of March, A. D. 1935.
